AUTOMATIC BOWLING PIN SETTER

Donald M. Came, Brookline, Mass., David E. O'Connor, Houston, Tex., and Donald Richardson, Winchester, Mass., assignors to Came Associates, Inc., Boston, Mass., a corporation of Massachusetts

Original application Dec. 5, 1955, Ser. No. 550,973. Divided and this application June 23, 1958, Ser. No. 743,810

23 Claims. (Cl. 273—43)

The present invention relates generally to automatic bowling pin setters, so-called, for use in connection with standard bowling alleys; and more particularly to improved mechanisms for the moving of bowling pins and bowling balls from a bowling alley bed and gutters into a bowling alley pit; for the assembling, from the bowling alley pit, and the setting upon the bowling alley bed, of the bowling pins; for the returning of the bowling balls from the bowling alley pit to the bowler's position; and for the clearing of fallen bowling pins from the bowling alley bed and gutters during a unit of play by and of the individual bowler.

The present application is a divisional application of our copending application, Serial No. 550,973, filed December 5, 1955, now abandoned.

The principal object of the present invention is to provide, for use in connection with standard bowling alleys comprising bowling alley beds, gutters, kickbacks, pits and bumpers, a combination of improved mechanisms, actuatable at the will of the bowler, that will perform the functions performed presently by pin-boys, so-called.

Another object of the present invention is to provide, for use in connection with standard bowling alleys comprising bowling alley beds, gutters, kickbacks, pits and bumpers, an improved bowling pins and bowling balls handling mechanism that will separate bowling pins and bowling balls delivered thereto, return the bowling balls to the bowler's position, and, at the will of the bowler, reset the bowling pins upon the bowling alley bed.

Another object of the present invention is to provide, for use in connection with standard bowling alleys comprising bowling alley beds, gutters, kickbacks, pits and bumpers, an improved bowling pins and bowling balls handling mechanism, comprising an improved bowling pins setting mechanism, and mechanism whereby and wherein a first full complement of ten bowling pins is held in readiness during the setting of a second full complement of ten bowling pins upon the bowling alley bed by the improved bowling pins setting mechanism, and then is delivered to, and into, the improved bowling pins setting mechanism after the setting, by the improved bowling pins setting mechanism, of the second full complement of ten bowling pins.

Another object of the present invention is to provide, for use in connection with standard bowling alleys comprising bowling alley beds, gutters, kickbacks, pits and bumpers, a combination of improved mechanisms, actuatable at the will of the bowler, that will remove bowling pins and bowling balls from the bowling alley bed after the bowling alley has been used in play, will retain less than, or reset in entirety, the full complement of ten bowling pins upon the bowling alley bed ready for further play, and will return the bowling balls to the bowler's position.

Another object of the present invention is to provide, for use in connection with standard bowling alleys comprising bowling alley beds, gutters, kickbacks, pits

2

and bumpers, a combination of improved mechanisms, actuatable at the will of the bowler, that will remove fallen bowling pins and bowling balls from the bowling alley bed after the bowling alley has been used in play, while retaining the standing bowling pins in their positions upon the bowling alley bed ready for further play, and will return the bowling balls to the bowler's position.

Another object of the present invention is to provide, for use in connection with standard bowling alleys comprising bowling alley beds, gutters, kickbacks, pits and bumpers, bowling pins setting mechanisms, which, in their cycle of bowling pins setting operations, sweep other bowling pins from the bowling alley, thus eliminating the necessity of providing separate bowling pins sweeping mechanisms to effectuate such sweeping operations.

Another object of the present invention is to provide, for the purposes described, a combination of improved mechanisms by and in the use of which the setting of the bowling pins upon the bowling alley bed and the returning of the bowling balls to the bowler's position will be effectuated at speeds greater than heretofore have been attained.

Another object of the present invention is to provide, for the purposes described, a combination of improved mechanisms that are so positioned with respect to the bowling alley bed as not to constitute any interference or distraction, physically, visually or otherwise, during the actual periods of play.

Another object of the present invention is to provide, for the purposes described, a combination of improved mechanisms that may be readily and rapidly installed in a standard bowling alley without necessitating the making of substantial alterations in or of the standard bowling alley bed, gutters and pit, nor the making of any alterations in or of the kickbacks and bumper, and without necessitating the requiring, or the utilizing, of any space above the bowling alley or behind the bumper.

Another object of the present invention is to provide, for the purposes described, a combination of improved mechanisms that may be readily and rapidly installed in a standard bowling alley as a substantially self-contained unit, without necessitating the making of alterations, in and of the standard bowling alley bed, gutters and pit, other than the replacement, by and with the self-contained unit, of a portion of the standard bowling alley bed and portions of the gutters proximate thereto having a total superficial area substantially equal to the superficial area of the self-contained unit, and the installation, in the bowling alley pit, of a bowling alley pit vibratory conveyor, and without the making of any alteration in or of the kickbacks and bumper.

Another object of the present invention is to provide a vibratory conveyor so compact and so self-counterbalanced as to permit of its utilization, among possible utilizations, in a bowling pin setting machine.

Another object of the present invention is to provide, for the purposes described, a combination of improved mechanisms which, when installed in a standard bowling alley, will not interfere in any way with the making of repairs to the bowling alley, such as the resurfacing of the bowling alley bed, and will not interfere in any way with the manual setting of bowling pins upon the bowling alley bed by pin-boys, so-called, when, if and as such manual setting of bowling pins upon the bowling alley bed may be desired.

Another object of the present invention is to provide, for the purposes described, a combination of improved mechanisms and appropriate means for properly coordinating their operations in and for the effectuating of such purposes.

The attainment of these and other objects of the present invention by the present invention will, to anyone skilled in the art to which it appertains, readily become apparent upon examination of the following specification and the accompanying drawings, constituting portions thereof, wherein are described and illustrated a preferred embodiment of the present invention, and variants of portions thereof coming within the scopes of the claims appended to the specification.

The present invention contemplates the inclusion of all of the specified mechanisms, save the mechanisms pertaining to the bowling alley pit vibratory conveyor and the bowling ball elevating mechanism, within, or as an intimate part of, a box-like structure, of width substantially equal to the distance between the kickbacks, so that the installation of such mechanisms requires simply the replacement, by and with the box-like structure, of a portion of the bowling alley, in length equal to the length, and in depth equal to the height, of the box-like structure. Some idea of the dimensions of the box-like structure, and of the compactness and self-containedness of the present invention, will be gained by an examination of the first three drawings: Fig. 1 comprises a plan view of the box-like structure, showing its length and width, and the pair of hinged bowling alley surface plates and the pair of hinged bowling pins spots plates, constituting, with the bowling alley gutter vibratory conveyors, the top, and serving as lids, of the box-like structure, and capable of tiltwise angular movement through substantially 90°; Fig. 2 comprises a lateral elevation of the box-like structure, showing its length and height; and Fig. 3 comprises a rear elevation of the box-like structure, showing its width and height, and showing the ingress thereto and into the bowling pins and bowling balls handling mechanisms contained therein.

Throughout the specification and the claims appended thereto, and in the accompanying drawings, the following definitions shall prevail:

(a) Right-hand and left-hand orientation of the present invention shall be taken to be that predicated by the bowler viewing the present invention from the bowler's position.

(b) The front and the rear of the present invention shall be taken to refer to the part of the present invention nearest to the bowler and the part of the present invention farthest from the bowler, respectively, when the bowler is occupying the bowler's position.

(c) All references to bowling pin members and to bowling pin spots shall be taken to refer to the bowling pins and to their locations as they are set for play upon the bowling alley bed, and the bowling pin numbers shall read from left to right and progressively along the bowling alley bed, the No. 1 bowling pin being the bowling pin nearest to, and the Nos. 7, 8, 9, 10 bowling pins being the bowling pins farthest from, when the bowler is occupying the bowler's position.

Fig. 1 is a plan view of the present invention, installed in a standard bowling alley, showing, from right to left, between the bowling alley kickbacks: the bowling alley bumper; the bowling alley pit vibratory conveyor in the bowling alley pit; the ingress for bowling pins and bowling balls to the bowling pins and bowling balls handling mechanisms through the rear (fourth) transverse bulkhead, which serves as the rear transverse structural member of the present invention, and as an end member of the box-like structure; the hinged bowling pins spots plates, with the full complement of ten bowling pins, shown in broken lines, set upon the hinged bowling pins spots plates in the usual triangular arrangement and numbered according to the conventional method of designating bowling pins set in positions for play; the hinged bowling alley surface plates, positioned between the hinged bowling pins spots plates and the bowling alley bed, proper; the bowling alley gutter vibratory conveyors, positioned adjacent to the hinged bowling pins spots

plates and the hinged bowling alley surface plates; the bowling alley bed, proper, and the bowling alley gutters, proper, and the bowling ball elevating mechanism and the bowling ball return track, both positioned adjacent to the left-hand bowling alley gutter, proper.

Fig. 2 is a right-hand side elevation, partly in section, taken along the line 2, 2, of Fig. 1, of the present invention, installed in a standard bowling alley, showing, from right to left: the bowling alley bumper; the bowling alley pit vibratory conveyor in the bowling alley pit; the rear (fourth) transverse bulkhead, which serves as the rear transverse structural member of the present invention, and as an end member of the box-like structure; the right-hand lateral structural member of the present invention, which serves as a side member of the boxlike structure; the right-hand hinged bowling pins spots plate, with four bowling pins, shown in broken lines, set upon the hinged bowling pins spots plates; the right-hand hinged bowling alley surface plates; the right-hand bowling alley gutter vibratory conveyor; the left-hand bowling alley kickback; the bowling ball elevating mechanism and the bowling ball return track, both positioned adjacent to the left-hand bowling alley gutter, proper; and details of construction of a standard bowling alley.

Fig. 3 is a rear elevation, partly in section, taken along the line 3, 3, of Fig. 1, of the present invention, installed in a standard bowling alley, showing, between the bowling alley kickbacks: the bowling alley pit vibratory conveyor in the bowling alley pit; the ingress for bowling pins and bowling balls to the bowling pins and bowling balls handling mechanisms through the rear (fourth) transverse bulkhead, which serves as the rear transverse structural member of the present invention, and as an end member of the box-like structure; the bowling alley gutter vibratory conveyors; seven bowling pins, shown in broken lines, set upon the bowling pins spots plates in positions for play; and, at the right-hand in the drawing, a portion of the housing of the bowling ball elevating mechanism, positioned adjacent to the left-hand bowling alley gutter, proper.

Fig. 4 is a front elevation, taken along the line 4, 4, of Fig. 1, of the present invention, installed in a standard bowling alley, showing, between the bowling alley kickbacks (the left-hand bowling alley kickback being partially hidden from view by the bowling ball elevating mechanism, whereby a bowling ball has just been elevated onto the ball return track), the front transverse end plate of the present invention, which serves as an end member of the box-like structure; the bowling alley gutter vibratory conveyors; the hinged bowling alley surface plates and the hinged bowling pins spots plates, both in the tilted positions attained in the clearing of fallen bowling pins from the playing surfaces of the hinged bowling alley surface plates and the hinged bowling pins spots plates, with two standing bowling pins held in their proper positions upon the hinged bowling pins spots plates by bowling pin traction magnets, and one fallen bowling pin lying upon the right-hand bowling alley gutter vibratory conveyor; and the ball guards, in their positions of maximum tilt.

Fig. 5 is a plan view of the present invention, installed in a standard bowling alley, showing, from right to left, between the bowling alley kickbacks: the bowling alley bumper; the bowling alley pit vibratory conveyor in the bowling alley pit, with two bowling pins and a bowling ball, shown in broken lines, thereupon; the ingress for bowling pins and bowling balls to the bowling pins and bowling balls handling mechanisms through the rear (fourth) transverse bulkhead, which serves as the rear transverse structural member of the present invention, and as an end member of the box-like structure; the hinged bowling pins spots plates; the bowling pins carrying and sweeping structure, in vertical position over the hinged bowling pins spots plates, returning from the rearmost position attainable in its carrying and sweeping cycle, after

it has swept into the bowling alley pit the two bowling pins and the bowling ball, and has released the bowling pins 7, 8, 9, 10, and while it is in the process of releasing the bowling pins 4, 5, 6, upon the hinged bowling pins spots plates; the hinged bowling alley surface plates, substantially vertical, in their positions of maximum tilt, but with their latching mechanisms upon their under sides omitted, in order not to obscure details of construction therebelow; the second transverse bulkhead, provided with seven apertures, and the front (first) transverse bulkhead, which serve as the second and first transverse structural members, respectively, of the present invention; the bowling pins carrying and sweeping structure receiving chamber, located between the second transverse bulkhead and the front (first) transverse bulkhead; the ball guards, in their positions of maximum tilt; the bowling alley gutter vibratory conveyors, positioned adjacent to the hinged bowling pins spots plates and the hinged bowling alley surface plates; the bowling alley bed, proper, and the bowling alley gutters, proper; and the bowling ball elevating mechanism and the bowling ball return track, both positioned adjacent to the left-hand bowling alley gutter, proper.

Fig. 6 is a front elevation, partly in section, taken along the line 6, 6 of Fig. 5, of the present invention, installed in a standard bowling alley, showing, between the bowling alley kickbacks: the bowling alley gutter vibratory conveyors, positioned adjacent to the bowling alley kickbacks; the hinged bowling alley surface plates (one of which is broken away) in their positions of maximum tilt; the right-hand ball guard, in its position of maximum tilt (the left-hand ball guard being omitted, in order not to obscure details of construction to the rear); the bowling pins carrying and sweeping structure, in vertical position over the hinged bowling pins spots plates; and the front traverse end plate of the present invention, which serves as an end member of the box-like structure.

Figs. 7a and 7b are left-hand and right-hand joinable sections of a plan view of a portion of the present invention, with the hinged bowling alley surface plates and the hinged bowling pins spots plates removed, and with the bowling alley gutters broken away, showing, comprised within the box-like structure, bowling pins and bowling balls handling mechanisms instrumental in attaining the objects of the present invention, and Fig. 7b showing, in particular, the preferred embodiment of the bowling balls and bowling pins separating and orientating mechanism, whereof two other embodiments are shown in analogous manner in the Figs. 48 and 51, respectively.

Figs. 8a and 8b are left-hand and right-hand joinable sections of a side elevation, partly in section, taken along the line 8, 8 of Fig. 5, of a portion of the present invention, installed in a standard bowling alley, showing, comprised within the box-like structure, bowling pins and bowling balls handling mechanisms instrumental in attaining the objects of the present invention, and Fig. 8b showing, in particular, the preferred embodiment of the bowling balls and bowling pins separating and orientating mechanism, whereof two other embodiments are shown in somewhat analogous manner in the Figs. 49 and 52.

Fig. 9 is an elevation, partly in section, taken along the line 9, 9 of Fig. 5, showing: the bowling alley gutter vibratory conveyors; the hinged bowling alley surface plates, substantially vertical, in their positions of maximum tilt; the hinged bowling alley surface plates tilting and detilting mechanisms for effecting the tilting and the detilting of the bowling alley surface plates; the hinged bowling alley surface plates latching mechanisms for latching together, in pairs, hinged bowling alley surface plates and hinged bowling pins spots plates; and, between them, the bowling pins carrying and sweeping structure, in vertical position, over the hinged bowling pins spots plates; the right-hand ball guard, in its position of maximum tilt; a portion of the bowling pins magazine mechanism, shown through four of the seven apertures in the second transverse bulkhead, or transverse structural mem-

ber, carrying a full complement of ten bowling pins, whereof six of the bowling pins, namely, the bowling pins 7, 4, 8, 5, 2, 1, are shown, and four of the bowling pins, namely, the bowling pins 9, 6, 10, 3 are hidden by a right-hand portion of the front (first) transverse bulkhead or transverse structural member; a right-hand portion of the front (first) transverse bulkhead, or transverse structural member, partly broken away to show the electric limit switch for regulating the operations of the hinged bowling alley surface plates tilting and detilting mechanisms; and, at the right-hand, a transverse section of the ball track, with a bowling ball shown thereupon, and, at the left-hand, the left-hand forward-and-reverse chain drive, driven by the third power means (not shown).

Fig. 10 is a view of a detail of Fig. 8a, showing a part of the horizontal portion, the arcuate portion, and a part of the vertical portion, of the right-hand bowling pin carrying and sweeping mechanism path of travel, all supported by the second transverse bulkhead, or transverse structural member, upon which the bowling pins carrying and sweeping structure travels in its carrying and sweeping cycle, and showing the engaging of the chain pin, carried by the right-hand forward-and-reverse chain drive, with a forked dog, mounted upon the right-hand end of the bowling pins carrying and sweeping structure, thus powering the operation of the right-hand end of the bowling pins carrying and sweeping mechanism in its carrying and sweeping cycle.

Fig. 11 is a transverse view of the chain-pin-carrying link of one of the forward-and-reverse chain drives which, with the chain-pin-carrying link of the other of the forward-and-reverse chain drives, powers, and effectuates the operation of, the bowling pins carrying and sweeping mechanism in its carrying and sweeping cycle.

Figs. 12 and 13 are elevations of the right-hand hinged bowling alley surface plate tilting and detilting mechanism for effecting the tilting and the detilting of the right-hand hinged bowling alley surface plate, showing, in Fig. 12, a portion of the right-hand bowling alley surface plate substantially vertical, in its position of maximum tilt, and showing, in Fig. 13, a portion of the right-hand hinged bowling alley surface plate, substantially horizontal, in its position of minimum tilt.

Fig. 14 is a plan view of the bowling alley pit vibratory conveyor, showing: the ensemble of three members, namely, the central member, provided with a prow, and the two lateral members, coupled by leaf springs, mounted upon the undersides, and obliquely inclined to the planes, of the central member and the two lateral members: the mountings of the lateral members upon spiral compression support springs; and the electromagnets, mounted upon the forward edges of the lateral members, and the armatures for the electromagnets, mounted upon the forward edge of the central member, for effecting vibrations in and of the ensemble of coupled members.

Fig. 15 is a rear elevation of the bowling alley pit vibratory conveyor, showing: the ensemble of three members, namely the central member, provided with a prow, gutter-like in conformation, and its transverse section shaped like a squat V, and the two lateral members, coupled by leaf springs, mounted upon the undersides of the central member and the two lateral members; the mountings of the lateral members upon spiral compression support springs; and, schematically, the electromagnets, mounted upon the forward edges of the lateral members, and the armatures for the electromagnets, mounted upon the forward edge of the central member, for effecting vibrations in and of the ensemble of coupled members.

Fig. 16 is a left-hand side elevation of the left-hand of the bowling alley pit vibratory conveyor, perpendicular to the plane of the left-hand lateral member of the bowling alley pit vibratory conveyor, showing: the ends of the several leaf springs, mounted upon the undersides, and obliquely inclined to the planes, of the central member and the left-hand lateral member; the mountings of

the left-hand lateral member upon spiral compression support springs; the electromagnet, mounted upon the forward edge of the left-hand lateral member, and the armature for the electromagnet, mounted upon the forward edge of the central member, for effecting vibration in and of the coupled left-hand lateral member and central member, and the prow, gutter-like in shape, of the central member.

Fig. 17 is an out-side lateral elevation, taken along the line 17, 17, of Fig. 1, of the rear end portion of the left-hand bowling alley gutter vibratory conveyor; three (of the six) angle drive springs, mounted transversely, and upon the undersides of, the two longitudinal members of the left-hand bowling alley gutter vibratory conveyor; an electromagnet and its armature, mounted upon the two thus-coupled longitudinal members, for effecting vibration in and of the two thus-coupled longitudinal members; and a spiral compression support spring, mounted upon a bracket (secured to the inner face of the left-hand lateral structural member (not shown) of the present invention, which serves as the left-hand lateral member of the box-like structure), for supporting the rear end portion of the out-side longitudinal member of the left-hand bowling alley gutter vibratory conveyor.

Fig. 18 is a plan view of the underside of the rear end portion of the left-hand bowling alley gutter vibratory conveyor, showing: the undersides of the rear end portions of the two longitudinal members of the left-hand bowling alley gutter vibratory conveyor; three (of the six) angle drive springs, mounted transversely, and upon the undersides, of the two longitudinal members of the left-hand bowling alley gutter vibratory conveyor; an electromagnet, secured to the in-side longitudinal member, and its armature, secured to the out-side longitudinal member, for effecting vibrations in and of the two thus-coupled longitudinal members; and two of the spiral compression support springs, mounted upon a bracket (secured to the inner face of the left-hand lateral structural member (not shown) of the present invention, which serves as the left-hand lateral member of the box-like structure), for supporting the rear end portions of the two longitudinal members of the left-hand bowling alley gutter vibratory conveyor.

Fig. 19 is an elevation, in cross-section, taken along the line 19, 19, of Fig. 18, of the rear end portion of the left-hand bowling alley gutter vibratory conveyor, showing: cross-sectional views of the two longitudinal members of the left-hand bowling alley gutter vibratory conveyor, the out-side longitudinal member, right side up, having a cross-sectional conformation resembling a reversed 4, and the in-side longitudinal member, right side up, having a cross-sectional conformation resembling a V having unequal arms, rotated through 45°; and an angle drive spring, mounted transversely, and upon the undersides, of the two longitudinal members of the left-hand bowling alley gutter vibratory conveyor.

Fig. 20 is a plan view, with the hinged bowling pins spots plates removed, of that portion of the present invention in the region of the prow, gutter-like in shape, of the bowling alley pit vibratory conveyor that extends beneath the front wall of the bowling alley pit, showing the ingress for bowling pins and bowling balls to the bowling pins and bowling balls handling mechanisms through the rear (fourth) transverse bulkhead, which serves as the rear transverse structural member of the present invention, and as an end member of the box-like structure, as well as the front wall of the bowling alley pit, and showing the pocket-like construction, comprising a forwardly extending bowling pin head-and-neck receiving recess, below, and in part beneath, the second chain lug conveyor, in part broken away, into which bowling pins and bowling balls are transmitted, unforcefully and individually, by the bowling alley pit vibratory conveyor.

Fig. 21 is an elevation, partly in section, taken along the line 21, 21, of Fig. 7b, showing the pocket-like con-

struction of Fig. 20, into which bowling pins and bowling balls are transmitted, unforcefully and individually, by the bowling alley pit vibratory conveyor, and the first chain lug conveyor, by which they are removed therefrom.

Fig. 22 is an elevation, partly in section, taken along the line 22, 22, of Fig. 7b, showing the second chain lug conveyor, a portion of the first chain lug conveyor, the common wall between the second chain lug conveyor and the first chain lug conveyor, and the passage therethrough, and the ball track.

Fig. 23 is an elevation, partly in section, taken along the line 23, 23, of Fig. 7b, showing the third (storage) chain lug conveyor, the second chain lug conveyor, the common wall between the third (storage) chain lug conveyor and the second chain lug conveyor, and the passage therethrough, and the ball track.

Fig. 24 is a plan view of the front (exit) end of the shorter portion of the third (storage) chain lug conveyor, showing: the arcuate portion of the walls thereof, adjoining the bowling pin receiving chute; and a portion of the bowling pin chute.

Fig. 25 is a transverse view, partly in section, taken along the line 25, 25, of Fig. 24, showing: a portion of the third (storage) chain lug conveyor, and the walls thereabout, and the aperture in an arcuate portion of one of the walls, permitting the passage therethrough of the chain and the lugs of the third (storage) chain lug conveyor; and a portion of the bowling pin chute.

Fig. 26 is an elevation, partly in section, taken along the line 26, 26, of Fig. 7b, showing from right to left: the lower, left-hand, rear portion of the bowling pins magazine mechanism, with a first bowling pin, shown in broken lines, resting in a conveyor pan thereof; the bowling pin injector mechanism, in its foremost position, with the bowling pin injector member within the bowling pin injector chamber and its pusher member in contact with the first bowling pin; the bowling pin chute receiving chamber, with a second bowling pin, shown in broken lines, positioned upon the floor thereof; the bowling pin chute, with a third bowling pin partially therein, but arrested in its passage to the bowling pin chute receiving chamber by the bowling pin chute stop mechanism; and the third (storage) chain lug conveyor, passing through the aperture in an arcuate portion of one of the walls thereof.

Fig. 27 is a plan view of the bowling pin injector feed mechanism and of a portion of the bowling pin injector mechanism in its foremost position, with a bowling pin, shown in broken lines, in the bowling pin chute receiving chamber, to be displaced, laterally, therefrom into the bowling pin injector chamber by the bowling pin injector feed mechanism, showing, from right to left: the bowling pin injector feed arm and the pusher member thereof, carrying a finger for contacting an electrical control actuating arm; the bowling pin injector feed arm actuating member; latching means between the bowling pin injector feed arm and the bowling pin injector feed arm actuating member; an electrical control actuating arm; the bowling pin injector member; yoking means between the bowling pin injector member and the bowling pin injector feed arm actuating member; and the serpentine chain drive.

Fig. 28 is a plan view of the bowling pin injector feed mechanism and of a portion of the bowling pin injector mechanism in its rearmost position, with a bowling pin, shown in broken lines, in the bowling pin injector chamber, showing, from right to left: the bowling pin injector feed arm and the pusher member thereof, carrying a finger for contacting an electrical control actuating arm; the bowling pin injector feed arm actuating member; latching means between the bowling pin injector feed arm and the bowling pin injector feed arm actuating member; an electrical control actuating arm; the bowling pin injector member; yoking means between the bowling pin injector member and the bowling pin injector feed arm actuating member; and the serpentine chain drive.

injector member and the bowling pin injector feed arm actuating member; and the serpentine chain drive.

Fig. 29 is an elevation, in section, taken along the line 29, 29, of Fig. 28, of the rear portion of the bowling pin injector mechanism, showing from right to left: the mode of actuation of the bowling pin injector feed arm actuating member by the bowling pin injector member through the yoking means between the bowling pin injector member and the bowling pin injector feed arm actuating member, and the mode of actuation of the bowling pin injector mechanism by the serpentine chain drive through the engagement of a chain pin thereon with the bowling pin injector mechanism.

Fig. 30 is a rear elevation, in section, of the bowling pins magazine mechanism, taken along the line 30, 30 of Fig. 8b, showing: the bowling pins magazine conveyor mechanism, for disposing into two parallel rows of seven bowling pins and three bowling pins, parallelly disposed, a full complement of ten bowling pins, and, in broken lines, a full complement of ten bowling pins so disposed and positioned upon conveyor pans of the bowling pins magazine conveyor mechanism; and electric control means for governing the operations of the bowling pins magazine conveyor mechanism.

Figs. 31, 32, 33, 34, are rear elevations of the left-hand portion of the bowling pins magazine mechanism, showing successive stages in the operations of the bowling pins magazine conveyor mechanism for disposing, into two parallel rows of seven bowling pins and three bowling pins parallelly disposed, a full complement of ten bowling pins, wherein the conveyor pans are carried from positions of definitive orientation in the upper level of positions to positions of definitive orientation in the lower level of positions.

Fig. 35 is a side elevation, taken along the line 35, 35, of Fig. 7b, of the left-hand end of the bowling pins magazine mechanism, showing: bowling pins magazine conveyor chains, with two conveyor pans mounted upon, and between, the bowling pins magazine conveyor chains; electrical control means for governing the operations of the bowling pins magazine conveyor mechanism; and, additionally, a portion of the bowling pins charging mechanism, for translating bowling pins from, and out of, the bowling pins magazine mechanism to, and into, the bowling pins carrying and sweeping structure, and a portion of the supporting structure therefor.

Fig. 36 is an elevation of the rear end of a conveyor pan of the bowling pins magazine conveyor mechanism, showing: the manner of the mounting of the conveyor pan upon the bowling pins magazine rear conveyor chain; and a pair of rollers, mounted upon the rear end of the conveyor pan of the bowling pins magazine conveyor mechanism, for engaging with cam surface members thereof to impart to the conveyor pan of the bowling pins magazine conveyor mechanism desired angular displacements about its longitudinal axis of rotation during the cycle of travel of the bowling pins magazine rear conveyor chain.

Fig. 37 is a side elevation of a conveyor pan, broken away, of the bowling pins magazine conveyor mechanism, showing, from right to left: the front end of the conveyor pan of the bowling pins magazine conveyor mechanism, and the manner of the mounting of the conveyor pan of the bowling pins magazine conveyor mechanism upon the bowling pins magazine front conveyor chain; an electrical control mechanism trip, positioned upon the front end of the conveyor pan of the bowling pins magazine conveyor mechanism, for actuating an electrical control mechanism (not shown); the body, in part, of the conveyor pan of the bowling pins magazine conveyor mechanism; the rear end of the conveyor pan of the bowling pins magazine conveyor mechanism, and the manner of the mounting of the conveyor pan of the bowling pins magazine conveyor mechanism upon the bowling pins magazine rear conveyor chain; and one of

the two rollers, mounted upon the rear end of the conveyor pan of the bowling pins magazine conveyor mechanism, for engaging with cam surface members thereof to impart to the conveyor pan of the bowling pins magazine conveyor mechanism desired angular displacements about its longitudinal axis of rotation during the cycle of travel of the bowling pins magazine rear conveyor chain.

Fig. 38 is an elevation of the front end of a conveyor pan of the bowling pins magazine conveyor mechanism, showing: the manner of the mounting of the conveyor pan of the bowling pins magazine conveyor mechanism upon the bowling pins magazine front conveyor chain; and an electrical control mechanism trip, positioned upon the front end of the conveyor pan of the bowling pins magazine conveyor mechanism, for actuating an electrical control mechanism (not shown).

Fig. 39 is a plan view of the bowling pins charging mechanism, showing the parallel, right and left, and center, supporting members, all broken away, upon which the bowling pins charging member travels, reciprocatingly, and which are themselves supported by the second and third transverse bulkheads, which serve as the second and third transverse structural members, respectively, of the present invention, as shown in the Fig. 8b, and by the second transverse bulkhead (second transverse structural member) and a vertical supporting member, respectively; the upper cross-member of the bowling pins charging mechanism, carrying the seven pusher members for translating into their positions in the bowling pins carrying and sweeping structure the seven bowling pins 10, 6, 9, 5, 8, 4, 7, parallelly disposed in the upper of the two parallel rows of bowling pins, parallelly disposed, in the bowling pins magazine mechanism, as shown in the Fig. 30; the upper arm of the longitudinally U-shaped member, as shown in the Fig. 40, interconnecting the upper cross member, carrying the seven pusher members, and the lower cross member, carrying the three pusher members for translating, into their positions in the bowling pins carrying and sweeping structure, the three bowling pins 3, 1, 2 parallelly disposed, in the bowling pins magazine mechanism, as shown in the Fig. 30; the serpentine chain drive, carrying chain pins, through whose engagements with the chain pin engaging mechanisms, positioned upon the arm secured to the longitudinally U-shaped member, as shown in the Fig. 40, the operations of the bowling pins charging mechanism are effectuated; and sundry electrical control mechanisms for governing the operations of the bowling pins charging mechanism.

Fig. 40 is a right-hand side elevation of the bowling pins charging mechanism, showing: the parallel, right and center, supporting members, both broken away, upon which the bowling pins charging member travels, reciprocatingly, and which are themselves supported by the second and third transverse bulkheads, which serve as the second and third transverse structural members, respectively, of the present invention, as shown in the Fig. 8b, and by the second transverse bulkhead (second transverse structural member) and a vertical supporting member, respectively; the longitudinally U-shaped member, interconnecting the upper cross member and the lower cross member, both carrying pusher members for translating into their positions in the bowling pins carrying and sweeping structure the ten bowling pins, parallelly disposed in the two parallel rows of bowling pins, parallelly disposed, in the bowling pins magazine mechanism, as shown in the Fig. 30; the serpentine chain drive, carrying chain pins, through whose engagements with the chain pin engaging mechanisms, positioned upon the arm secured to the longitudinally U-shaped member, as shown in the Fig. 40, the operations of the bowling pins charging mechanism are effectuated; and sundry electrical control mechanisms for governing the operations of the bowling pins charging mechanism.

Fig. 41 is a plan view of a portion of the bowling pins charging mechanism, as shown in the Fig. 39, but with the bowling pins charging member slightly displaced, leftwardly, showing: the engagement of a chain pin, carried by the serpentine chain drive, with the chain pin engaging mechanisms, positioned upon the arm secured to the longitudinally U-shaped member, contrasting with the non-engagement of a chain pin, carried by the serpentine chain drive, with the chain pin engaging mechanisms, positioned upon the arm secured to the longitudinally U-shaped member, as shown in the Figs. 39 and 40.

Fig. 42 is a plan view of a detail of construction disclosed in the Fig. 41, showing two members (one broken away) of the chain pin engaging mechanisms, positioned upon the arm secured to the longitudinally U-shaped member, with a chain pin, engaged and moving leftwardly the bowling pins charging member, translating bowling pins from the bowling pins magazine mechanism into the bowling pins carrying and sweeping structure.

Fig. 43 is a plan view of the left-hand portion of the bowling pins carrying and sweeping structure, in vertical position, that effectuates the carrying of the bowling pins 7, 8, 4, 2, onto, and over, the hinged bowling pins spots plates, showing: the bowling pins receiving, holding, and releasing devices, operative in the setting of the bowling pins 7, 8, 4, 2, upon the hinged bowling pins spots plates; and the forked dog, carried by the bowling pins carrying and sweeping structure on its left-hand end, through whose engagement with a chain pin, carried by the left-hand forward-and-reverse chain drive, the operation of the left-hand end of bowling pins carrying and sweeping mechanism in its carrying and sweeping cycle, is powered.

Fig. 44 is a plan view of that portion of the bowling pins carrying and sweeping structure, in vertical position, that effectuates the carrying of the bowling pins 8, 2, onto, and over, the hinged bowling pins spots plates, showing: the bowling pins receiving, holding, and releasing devices, operative in the setting of the bowling pins 8, 2, upon the hinged bowling pins spots plates, in the positions attained, after the bowling pin 8 has been set, and just as the bowling pin 2 is being set.

Fig. 45 is a vertical section of two of the bowling pin receiving chambers of the bowling pins carrying and sweeping structure, taken along the line 45, 45, of Fig. 43, showing: the bowling pin receiving chamber, for receiving and holding the bowling pin 2, formed by the semi-bowling-pin-shaped recess in the bowling pins carrying and sweeping structure and inner doors, provided with fingers integral therewith; and the bowling pin receiving chamber, for receiving and holding the bowling pin 8, formed by plates, longitudinally pivoted upon the inner doors, the inner doors and the plates being spring-constrained, and outer doors, spring-constrained, and provided with fingers integral therewith, the outer doors also serving as bowling pins impingement plates in the sweeping operation of the bowling pins carrying and sweeping mechanism.

Fig. 46 is a vertical section through a portion of a bowling pins spots plate, carrying a bowling pin traction magnet, and a bowling pin thereupon, taken along the line 46, 46, of Fig. 5, showing the iron ring, embedded in the base of the bowling pin, which serves as an armature of the bowling pin traction magnet, utilizable in the setting of bowling pins upon the bowling pins spots plate by the bowling pins carrying and sweeping mechanism.

Fig. 47 is a vertical section through a portion of a bowling pins spots plate, carrying a solenoid-operated pin spotting device, and a bowling pin thereupon, showing another construction, alternative to the bowling pin traction magnet and the bowling-pin-carried iron armature, utilizable in the setting of bowling pins upon the bowling pins spots plate by the bowling pins carrying and sweeping mechanism of the present invention.

Fig. 48 is a plan view, analogous to a portion of the plan view shown in the Fig. 7b, showing a second em-

bodiment of the bowling balls and bowling pins separating and orientating mechanism, utilizing an impacting mechanism.

Fig. 49 is a right-hand end elevation, taken along the line 49, 49, of Fig. 48, of the second embodiment of the bowling balls and bowling pins separating and orientating mechanism, utilizing an impacting mechanism.

Fig. 50 is a side elevation, taken along the line 50, 50, of Fig. 48, of the second embodiment of the bowling balls and bowling pins separating and orientating mechanism, utilizing an impacting mechanism.

Fig. 51 is a plan view, analogous to a portion of the plan view shown in the Fig. 7b, showing a third embodiment of the bowling balls and bowling pins separating and orientating mechanism, utilizing a dual belt conveyor.

Fig. 52 is a right-hand end elevation, taken along the line 52, 52, of Fig. 51, of the third embodiment of the bowling balls and bowling pins separating and orientating mechanism, utilizing a dual belt conveyor.

Fig. 53 is a side elevation, taken along the line 53, 53, of Fig. 51, of the third embodiment of the bowling balls and bowling pins separating and orientating mechanism, utilizing a dual belt conveyor.

Fig. 54 is a wiring diagram of the present invention.

Fig. 55 is an enlarged detail of a part of the wiring diagram shown in the Fig. 54, showing the Scott connected type of three phase to four phase transformers, a choke, four fuses, and the six rectifiers, four of which afford full wave rectified direct current and the other two of which afford half wave interrupted current.

In the several drawings are shown the rear portion of a standard bowling alley and auxiliary constructions, comprising the bowling alley bed 11, the two bowling alley gutters 12, the two kickbacks 13, the two bowling alley divisions 14, extensions of the two kickbacks 13, separating the bowling alley from adjacent bowling alleys, the bowling alley pit 15 at the rear of the bowling alley, the bumper 16 at the rear of the bowling alley pit 15, the bowling ball return track 17, the bowling alley leveler 18, the bowling alley screed 19 forming a part of the foundation of the standard bowling alley, and the floor 20 of the building wherein the standard bowling alley is installed. The assemblage of the bowling alley bed 11 and the bowling alley ancillary structures specified and the bowling alley bed supporting structures, all positioned beneath the surface of the bowling alley bed 11 and above the surface of the floor 20 of the building wherein the standard bowling alley is installed, is hereinafter termed "the bowling alley bed construction."

It is believed that the utmost clarity in effecting the disclosure of the present invention can best be attained by setting forth, in appropriate sequence, the descriptions of the several cooperating mechanisms whereof it is comprised, and statements of the purposes and functions for which they are utilized and the results attained by their utilization.

The bowling alley pit vibratory conveyor

As is shown in some detail in the Figs. 1, 2, 3, 5, and more clearly and in greater detail in the Figs. 14, 15, 16, the bowling alley pit vibratory conveyor, positioned in the bowling alley pit 15, at the rear of the box-like structure comprising the bowling pins and bowling balls handling mechanisms, comprises the two lateral members 31, 32, whose cross sections are substantially rectilinear, and the central member 33, obtusely dihedral and symmetrical, whose longitudinal cross sections are substantially rectilinear and whose transverse cross sections are squatly V-shaped in conformation: the masses of the two lateral members 31, 32, are substantially identical, and the sum of the masses of the two lateral members 31, 32, is substantially equal to, or slightly greater than, the mass of the central member 33. Each of the two lateral members 31, 32, is coupled with the central member 33, by means of a plurality of leaf-springs 34, mounted at 35

or 36 upon the underside, and transversely inclined to the plane, of the lateral member 31 or 32, and mounted at 37 or 38 upon the underside, and transversely inclined to one of the planes, of the central member 33, in the manners shown in the drawings; and the resulting ensemble of lateral members 31, 32, and central member 33, is mounted upon the spiral compression support springs 39, within the spring housings 40, secured to the undersides of the lateral members 31, 32, and the spring housings 41, mounted upon the angle iron strips 42, affixed to the floor 20, of the building wherein the standard bowling alley is installed. Upon the forward edges of the two lateral members 31, 32, are mounted the two electromagnets 43, 44, and upon the forward edge of the central member 33, are mounted the two armatures 45, 46, for the two electromagnets 43, 44. At the middle region of the forward edge of the central member 33, the central member 33 is formed into, or is otherwise provided with, an extension or prow 47, gutter-like in conformation. The bowling alley pit vibratory conveyor, heretofore described, is longitudinally inclined, downwardly towards its forward edges, at a slight angle, and its forward end portion extends forwardly beneath the rear (fourth) transverse bulkhead, or rear (fourth) transverse structural member 48, and the prow 47 extends measurably beneath the ingress 49 to the bowling pins and bowling balls handling mechanisms through the rear (fourth) transverse bulkhead, or rear (fourth) transverse structural member 48, which constitutes both an end member of the box-like structure and the front wall of the bowling alley pit 15. By selection of lateral members 31, 32, and central member 33, of suitable masses, and leaf-springs 34 of suitable flexibilities, the natural frequency of oscillation of the ensemble of lateral members 31, 32, and central member 33, can be predetermined and selected, so that the impression, upon suitably designed electromagnets 43, 44, of adequate size, of a current of electricity of frequency substantially identical with the natural frequency of oscillation of the ensemble of lateral members 31, 32, and central member 33, will cause the ensemble of lateral members 31, 32, and central member 33, to oscillate with resonance, not in the planes of the lateral members 31, 32, and/or the central member 33, but so that each particle of the lateral members 31, 32, and of the central member 33, will oscillate in some plane angularly disposed to the plane of the lateral member, 31 or 32, or of the central member 33, whereof it constitutes a particle. The purpose for the creation, and the function, of oscillations of such character in the ensemble of lateral members 31, 32, and central member 33, constituting the bowling alley pit vibratory conveyor, is to cause bowling pins and bowling balls, resting upon the bowling alley pit vibratory conveyor, to be impelled toward, and, unforcefully and individually, through the ingress 49 to bowling pins and bowling balls handling mechanisms through the rear (fourth) transverse bulkhead, or rear (fourth) transverse structural member 48.

The bowling alley gutter vibratory conveyors

As is shown in the Figs. 1, 2, 3, 4, 5, 6, 7b, 9, and particularly in the Figs. 17, 18, 19, each of the two bowling alley gutter vibratory conveyors, constituting portions of the top of the box-like structure comprising the bowling pins and bowling balls handling mechanisms, and constituting continuations, to the bowling alley pit 15, of the bowling alley gutters 12, comprises an out-side longitudinal member 51 and an in-side longitudinal member 52, whose masses are substantially identical, and whose upper surfaces lie in parallel planes spaced minutely apart in part. Each pair of the two longitudinal members, 51 and 52, are coupled, by means of a plurality of angle drive springs 53, mounted upon the undersides of the two longitudinal members, 51 and 52, in the manner shown in the Figs. 17 and 18; and the resulting

ensemble of two longitudinal members, 51 and 52, is mounted upon spiral compression support springs 54, within the spring housings, 55, secured to the undersides of the two longitudinal members, 51 and 52, and the spring housings 56, mounted upon the brackets 57, the brackets 57 being themselves mounted upon the inner surface of one of the two lateral structural members 58, as shown in the Figs. 7a, 7b, 8a, 8b, 9 and the spiral compression support springs 54 being pincentered with the pin 59. Near the forward end, and upon the underside, of the in-side longitudinal member 52 is mounted, rigidly, an electromagnet 60, which extends beneath, but is unattached to, the out-side longitudinal member 51; and near the forward end, and upon the underside, of the out-side longitudinal member 51 is mounted, rigidly, an armature 61, which extends beneath, but is unattached to, the in-side longitudinal member 52. By selection of longitudinal members 51, 52, of suitable masses, and angle drive springs 53, of suitable flexibilities, the natural frequency of oscillation of the ensemble of longitudinal members, 51 and 52, can be predetermined and selected, so that the impression, upon a suitably designed electromagnet 60, of a current of electricity of frequency substantially identical with the natural frequency of oscillation of the ensemble of longitudinal members, 51 and 52, will cause the ensemble of longitudinal members, 51 and 52, to oscillate with resonance, not in the plane of the longitudinal members, 51 and 52, but so that each particle of the two longitudinal members, 51 and 52, oscillates in a plane angularly disposed to the plane of the longitudinal members, 51 and 52, whereof it constitutes a particle. The purpose for the creation, and the function, of oscillations of such character in the ensemble of longitudinal members, 51 and 52, constituting either of the bowling alley gutter vibratory conveyors, is to cause bowling pins and bowling balls, resting upon that bowling alley gutter vibratory conveyor, to be impelled toward, and into, the bowling alley pit 15.

The bowling pins and bowling balls aligning, separating, and orientating mechanisms

Bowling pins and bowling balls, discharged into the bowling alley pit 15 are impelled, by the bowling alley pit vibratory conveyor, toward, and, unforcefully and individually, through the ingress 49 to the bowling pins and bowling balls handling mechanisms through the rear (fourth) transverse structural member 48, which constitutes both an end member of the box-like structure and the front wall of the bowling alley pit 15, thus becoming aligned, but not necessarily separated, in arriving at the first of the bowling pins and bowling balls handling mechanisms, namely, the bowling pins and bowling balls separating and orientating mechanisms.

As is shown in the Figs. 7b, 8b, 48, 51, and particularly in the Figs. 20, 21, 22, 23, the several embodiments of the bowling pins aligning, separating, and orientating mechanisms comprise a pocket-like structure into which are discharged, downwardly from and off of, the prow 47 of the bowling alley pit vibratory conveyor, individually, bowling balls and bowling pins, indiscriminately base foremost and head foremost. The construction of the pocket-like structure is such that a bowling ball, entering thereto through the ingress 49, or a bowling pin, head foremost, entering thereto through the ingress 49, will be wholly received therein and thereby; but a bowling pin, base foremost, entering thereto through the ingress 49, will be but partially received therein and thereby, and the head, and a portion of the neck, of such bowling pin will rest upon the prow 47 of the bowling alley pit vibratory conveyor and may protrude from the ingress 49. Such results are attained by the utilization of a pocket-like structure of depth and height sufficient to receive wholly therein a bowling ball and provided with a bowling pin head-and-neck-receiving recess communi-

eating therewith. Such construction is shown in the specified drawings, and particularly in the Fig. 20, wherein the pocket-like structure is shown as formed by the wall 71, a forward lower portion of which constitutes a wall of the bowling pin head-and-neck-receiving recess, and the wall 72, the lower edge of which is spaced from the floor 73 a distance greater than the diameter of the head, but less than the diameter of the belly, of a bowling pin, while the bowling pin head-and-neck-receiving recess is shown as formed by the wall 71, the floor 73, the end wall 74, and its continuation 75, while the floor 76 of the conduit of a (second) endless chain lug conveyor, presently to be described, lies directly above it. The pocket-like structure has a conformation such that a bowling ball, or the belly of a bowling pin deposited therein, from, and off of, the prow 47, is maintained in a position, directly in front of the prow 47, until it is removed, in a manner to be described presently, thus preventing the entry, into the pocket-like structure, of another bowling ball or bowling pin, while the pocket-like structure is already occupied by the previously deposited bowling ball or bowling pin.

As is shown in the Figs. 8b and 20, the pocket-like structure constitutes the lower end portion of a sloping conduit, formed by the floor 73 and the wall 72 and the wall-like member 77, through which travel the lugs 78, mounted upon, projecting from, and perpendicular to the vertical plane of travel of, the rear (first) endless chain lug conveyor 79, a lug 78 serving to impel, individually, either a bowling ball or a bowling pin, indiscriminately base foremost or head foremost, upwardly, until it is displaced, laterally, and the bowling pin is turned substantially through a right angle, by the combined action of the lug 78 and the arcuate portion 80 of the wall-like member 77, through the passage between the end of the wall 72 and the arcuate portion 80 of the wall-like member 77, in width intermediate the length, and the diameter of the belly, of a bowling pin, down onto, and over, the ramp-like member 81, and onto the floor 76 of the conduit of the second endless chain lug conveyor, at 82 only slightly inclined downwardly, wherefrom a bowling ball is discharged, by gravity, downwardly, onto a ball track 83, and whereupon a bowling pin remains, disposed in either of the two positions, substantially as is shown in broken lines in the Fig. 7b, and held thus by frictional forces on the floor of the conduit of the second endless chain lug conveyor. The conduit of the second endless chain lug conveyor is formed by the walls 72 and 84 and the sloping floor 76, in the middle of which travels, in a vertical plane of travel, the second endless chain lug conveyor 85, upon which are mounted the pushing lugs 86. When a bowling pin has attained one or the other of the two positions shown at 82 in the Fig. 7b, the pushing lug 86, acting upon the belly of a bowling pin, impels it upwardly upon the sloping floor 76 of the conduit of the second endless chain lug conveyor 85, and, in so doing, orients it base foremost. For if a bowling pin is in either of the two positions shown at 82 in the Fig. 7b, force exerted by a pushing lug 86 upon the belly of the bowling pin will impel it upwardly upon the sloping floor 76 of the conduit of the second endless chain lug conveyor 85, and, in so doing, will cause the bowling pin head, or the bowling pin neck, to make contact with either the wall 84, or the end of the wall 72, respectively, both of these elements, 84 and 72, thus serving as baffle means reacting upon the upper portions of the bowling pin; and thus the bowling pin will be turned, so that its base is foremost with respect to the direction of its travel. And since bowling balls and bowling pins are delivered, individually, onto the floor of the conduit of the second endless chain lug conveyor 85 at 82, and since the operations of the first and the second endless chain lug conveyors, 79 and 85, are synchronized (they are driven at constant speeds by the same power shaft), the move-

ments of their respective lugs, 78 and 86, are likewise synchronized, and there can be no interference between bowling pin and bowling ball, nor between bowling pin and bowling pin, nor between bowling ball and bowling ball, nor between a pushing lug 86 of the second endless chain lug conveyor 85 and a bowling ball, nor between a pushing lug 86 of the second endless chain lug conveyor 85 and the neck of a bowling pin. Each bowling pin, orientated base foremost, is impelled upwardly upon the sloping floor 76 of the conduit of the second endless chain lug conveyor 85 by a pushing lug 86, until it is displaced, laterally, by the combined actions of the pushing lug 86 and the portion of the wall 72 that is angularly athwart the second endless chain lug conveyor 85, through the passage between the end of the wall 84 and the end of the portion of the wall 72 that is angularly athwart the second endless chain lug conveyor 85, in width measurably greater than the length of a bowling pin, down, and off of, the sloping floor 76 of the conduit of the second endless chain lug conveyor 85, onto the horizontal floor of the conduit of the third (storage) endless chain lug conveyor; and, in such displacements, the orientation of the bowling pin with respect to the direction of its possible travel is reversed, because the direction of its possible travel upon the third (storage) endless chain lug conveyor is the reverse of the direction of its previous travel upon the second endless chain lug conveyor 85. Due to the forces acting and reacting upon the bowling pin during such displacements, laterally and downwardly, there is some tendency for the prone bowling pin to oscillate in a horizontal plane, but such oscillations are substantially eliminated by the provision of a deflecting member 87, positioned at the entrance end of the conduit of the third (storage) endless chain lug conveyor, wherewith the base end of the bowling pin comes into contact as the bowling pin leaves the sloping floor 76 of the conduit of the second endless chain lug conveyor, 85, and by the dropping of the belly of the bowling pin onto the floor of the conduit of the third (storage) endless chain lug conveyor.

Although the drawings and the description show most of the length of the floor 73 and all of the length of the floor 76 of the conduits of the first and second endless chain lug conveyors, 79 and 85, to be sloping upwardly in the directions of travel of bowling pins, it should be understood, that, except for the slight inclinations of the lower ends of the floors, 73 and 76, the marked inclinations accorded to the conduits of the first and second endless chain lug conveyors, 79 and 85, constitute no indispensable feature of the present invention, and are not to be construed as limitations thereto.

The purposes and functions of the bowling pins aligning, separating, and orientating mechanisms are, obviously, to effect the separation of bowling balls from bowling pins, and, less obviously, to effect alignment and orientation of bowling pins such as to permit them to be handled, individually and uniformly, by the bowling pins setting mechanisms to whose operations they are subsequently subjected.

The third (storage) endless chain lug conveyor

As is shown most fully in the Figs. 7b, 8b, 23, 26, the conduit of the third (storage) endless chain lug conveyor is formed by the walls 84 and 88 and the horizontal floor 89, in the middle of which travels, at a speed that varies periodically from approximately zero to a maximum to approximately zero, in a horizontal plane of travel, the third (storage) endless chain lug conveyor 90, upon which are mounted the low lugs 91. When a bowling pin has been discharged, by gravity, down, and off of, the second endless chain lug conveyor 85 onto the horizontal floor 89 of the third (storage) endless chain lug conveyor 90, the bowling pin, orientated head foremost in the direction of possible travel of the bowling pin upon the third (storage) endless chain lug conveyor 90, is impelled in

the direction of possible travel until either it is discharged, head foremost, from the exit end of the conduit of the third (storage) endless chain lug conveyor 90, or is held thereat, or thereon, either by a bowling pin stop mechanism, positioned adjacent to the exit end of the conduit of the third (storage) endless chain lug conveyor 90, if the bowling pin is about to emerge from the exit end of the conduit of the third (storage) endless chain lug conveyor 90, or by bowling pins, orientated heads foremost and aligned, in positions preceding the position of that bowling pin upon the third (storage) endless chain lug conveyor 90; whereupon all of the bowling pins, thus orientated and aligned upon the third (storage) endless chain lug conveyor 90, maintain their relative positions, while the low lugs 91 slip beneath the bowling pins, raising them off of, and dropping them back onto, the horizontal floor 89 of the conduit of the third (storage) endless chain lug conveyor 90. As is implied by the mode and manner of its designation, the purposes and the functions of the third (storage) endless chain lug conveyor 90 and the conduit therefor are to permit the accumulation, and to maintain in reserve, under appropriate operating conditions, a supply of bowling pins, properly orientated and aligned, within the bowling pin setting machine.

The bowling pin chute and the bowling pin chute receiving chamber

As is shown in the Figs. 7b, and 24, the exit end of the conduit of the third (storage) endless chain lug conveyor 90 comprises an arcuate section leading to a bowling pin chute receiving chamber 93, positioned therebelow. As a bowling pin, orientated head foremost, upon the third (storage) endless chain lug conveyor 90, approaches the bowling pin chute 92, by the combined action of the third (storage) endless chain lug conveyor 90 and the arcuate portion 94 of the inner vertical wall 88 of the conduit of the third (storage) endless chain lug conveyor 90, the bowling pin is turned through a right angle, and the bowling pin, orientated head foremost, then plunges, down the bowling pin chute 92, and into the bowling pin chute receiving chamber 93—provided, however, that the bowling pin chute receiving chamber 93 does not already contain a bowling pin; in which contingency, the bowling pin has become barred from entering the bowling pin chute 92 by a bowling pin chute stop mechanism 95, positioned adjacent to the exit end of the conduit of the third (storage) endless chain lug conveyor 90 and just above the bowling pin chute 92, and comprising a spring-return, pusher member, solenoid actuated through an electric limit switch 96, maintained activated by the bowling pin already in the bowling pin chute receiving chamber 93, with its head in force-exerting contact with the electric limit switch actuating arm 97, operative in the bowling pin chute receiving chamber 93. And when the bowling pin already in the bowling pin chute receiving chamber 93 is displaced, laterally, into the bowling pin injector chamber 98, positioned adjacent and parallel thereto, and communicating therewith, by the bowling pin injector feed mechanism, shown in the Figs. 27 and 28, the electric limit switch 96, now activated, is maintained activated by a finger 99, mounted upon the bowling pin injector feed arm pusher member 100, traveling upon and over a cam surface 101 upon the electric limit switch actuating arm 97, operative in the bowling pin chute receiving chamber 93, in and during both the forward movement and the return movement of the bowling pin injector feed arm pusher member 100 in the bowling pin chute receiving chamber 93. But at the conclusion of the return movement of the bowling pin injector feed arm pusher member 100, the contact between the finger 99, and the cam surface 101 is broken, and the restoring spring of the electric limit switch actuating arm 97, operative in the bowling pin chute receiving chamber 93, causes the electric

limit switch 96 to become opened; whereupon the pusher member of the bowling pin chute stop mechanism 95 is spring-withdrawn, and the bowling pin, orientated head foremost, heretofore barred from entering the bowling pin chute 92, now plunges, head foremost, down the bowling pin chute 92 and into the bowling pin chute receiving chamber 93, its head making force-exerting contact with, and moving rotatably the electric limit switch actuating arm 97, operative in the bowling pin chute receiving chamber 93, which closes the electric limit switch 96, normally open, and energizes the bowling pin chute stop mechanism 95, to bar the following bowling pin, orientated head foremost, from entering the bowling pin chute 92.

The purpose and the function of the bowling pin chute 92 and the bowling pin chute receiving chamber 93 and their ancillary mechanisms are to provide a regulated sequence of bowling pins, properly orientated, to a bowling pin injector feed mechanism, to be fed thereby into a bowling pin injector mechanism.

The bowling pin injector feed mechanism

As is shown in the Figs. 7b, 27, 28, the bowling pin injector feed mechanism comprises: the bowling pin injector feed arm 102, mounted bearingly at 103 and provided at one of its ends with the pusher member 100, carrying the finger 99 and travelling in the bowling pin chute receiving chamber 93, as has already been set forth, the bowling pin injector feed arm actuating member 104, mounted bearingly at 103, and having mounted rigidly upon it at one of its ends the V-shaped channel cam member 105, wherein travels the cam roller 106, mounted bearingly upon the crosshead member 107 of the bowling pin injector member 108, capable of being reciprocated in the bowling pin injector chamber 98, as will be described presently, thus powering the bowling pin injector feed arm actuating member 104, when the bowling pin injector member 108 is reciprocated in the bowling pin injector chamber 98; and an electromagnet 109 and an armature 110 therefor, distributed between the bowling pin injector feed arm actuating member 104, and the bowling pin injector feed arm 102, as is shown in the Figs. 27, 28, and energizable through electrical control means, positioned and actuated in the bowling pins magazine mechanism, subsequently to be described; the electromagnet 109 being in series with the electric limit switch 96, actuated through the electric limit switch actuating arm 97, operative in the bowling pin chute receiving chamber 93, and, when energized, capable of uniting the bowling pin injector feed arm actuating member 104 and the bowling pin injector feed arm 102 into a single member, mounted bearingly at 103 and powered, when the bowling pin injector member 108 is reciprocated in the bowling pin injector chamber 98, through the cam roller 106, bearingly mounted upon the crosshead member 107 of the bowling pin injector member 108 and travelling in the V-shaped channel cam member 105 of the bowling pin injector feed arm actuating member 104.

As is shown in the Fig. 7b, and has already been stated, the bowling pin chute receiving chamber 93 and the bowling pin injector chamber 98, both of dimensions adequate to permit each of the to receive a single bowling pin, and positioned adjacent and parallel to one another, communicate with one another through a side common to both chambers: the floors of both the bowling pin chute receiving chamber 93 and the bowling pin injector chamber 98 are transversely concave upwardly, so that when a bowling pin is displaced, laterally, from the bowling pin chute receiving chamber 93 to the bowling pin injector chamber 98, through the side common to both chambers, the bowling pin is elevated over the longitudinal ridge lying in the plane of the side common to both chambers, separating, and in a sense defining, the two chambers.

As will subsequently become apparent, the purpose and the function of the bowling pin injector feed mechanism are to supply to the bowling pin injector mechanism bowling pins, individually, under conditions of demand imposed by other mechanisms cooperating therewith.

The bowling pin injector mechanism

As is shown in the Figs. 7b, 26, and particularly in the Figs. 27, 28, 29, the bowling pin injector mechanism comprises: the bowling pin injector member 108, moving reciprocatingly and pistonwise between the horizontal guides 111 and travelling through the bowling pin injector chamber 98, and provided at its rear, or head, with a cross head member 107, forming therewith an L, the cross head member 107 carrying on its upper face the cam roller 106, mounted bearingly thereupon, and carrying upon its lower face the two chain pin engaging plates, 112 and 113, the chain pin engaging plate 112 acting, with a chain pin 114, carried by the serpentine chain drive 115, here disposed, in a conformation shaped like a U with rounded ends, upon sprocket wheels, and driven at a speed that varies periodically from approximately zero to a maximum to approximately zero, as a cam plate for the withdrawing of the bowling pin injector member 108 from the bowling pin injector chamber 98, and the chain pin engaging plate 113, acting with a chain pin 114, carried by the serpentine chain drive 115, as a cam plate for the advancing of the bowling pin injector member 108, upon the front of which is mounted the forwardly inclined pusher member 116, into the bowling pin injector chamber 98 and the injection of a bowling pin, whenever therein, into the bowling pins magazine mechanism, as will be described subsequently. Comitantly with these operations, the cam roller 106, mounted bearingly upon the upper face of the crosshead member 107, travels to and fro in the V-shaped channel cam member 104, causing the bowling pin injector feed arm actuating member 104, to oscillate upon its bearing at 103; but if and when the electromagnet 109 is energized, causing both the bowling pin injector feed arm actuating member 104 and the bowling pin injector feed arm 102, united, as it were, into a single member, to oscillate upon their bearings at 103, and thus causing the bowling pin injector feed arm pusher member 98, moving transversely through the bowling pin chute receiving chamber 93, to displace, laterally, out of the bowling pin chute receiving chamber 93 into the bowling pin injector chamber 98, a bowling pin, whenever a bowling pin is in the bowling pin chute receiving chamber 93, and then to return to its initial, or rest, position in the bowling pin chute receiving chamber 93, as is shown in the Fig. 27.

During the movements of the bowling pin injector feed arm pusher member 100 in the bowling pin chute receiving chamber 93, the entry of a bowling pin into the bowling pin chute receiving chamber 93, by way of the bowling pin chute 92, has been barred by the bowling pin chute stop mechanism 95, maintained energized through the electric limit switch 96, maintained activated by the finger 99, mounted upon the bowling pin injector feed arm pusher member 100, travelling upon and over the cam surface 101 upon the electric limit switch actuating arm 97, operative in the bowling pin chute receiving chamber 93, as has already been stated.

As will subsequently become apparent, the purposes and the functions of the bowling pin injector mechanism are to receive, individually, and to inject, individually, into a bowling pins magazine mechanism, bowling pins, whenever, in response to conditions of demand imposed by other mechanisms, bowling pins are individually delivered, to the bowling pin injector mechanism for such injecting into the bowling pins magazine mechanism.

The bowling pins magazine mechanism

As is shown in the Figs. 7a, 7b, 8a, 8b, 26, 30, 31-38,

the bowling pins magazine mechanism, into which bowling pins, individually, are injected by the bowling pins injector mechanism, comprises parallel front and rear endless bowling pins magazine conveyor chains, 120 and 121, mounted for movement along paths substantially trapezoidal in conformation, linked transversely by the bowling pin conveyor pans 122, bearingly mounted upon the bowling pin conveyor chain pins 123, of the front and rear bowling pins magazine chains, 120 and 121, and driven in a manner explained subsequently. The pairs 5 of rollers 124, bearingly mounted upon the rear ends of the bowling pin conveyor pans 122, travel upon, and are supported by, the interrupted horizontal tracks, 125 and 126, comprising channel members and bars, positioned transversely of the bowling alley and mounted upon the front face of the third transverse bulkhead, or third transverse structural member 127, of the present invention. The rear bowling pins magazine conveyor chain 121 is supported by, and runs anti-clockwise, as viewed from the front, upon four supporting sprockets, bearingly mounted upon the front face of the third transverse bulkhead, or third transverse structural member 127, one of which supporting sprockets is keyed to the front end of a rearwardly-directed shaft, to the rear end 10 of which shaft is keyed another sprocket, which is driven by the driving chain 128. Another of the four supporting sprockets of the rear bowling pins magazine conveyor chain 121 is keyed to the rear end of a forwardly directed shaft 129, to effect rotation of the forwardly directed shaft 129 during movement of the rear conveyor chain 121. The front bowling pins magazine conveyor chain 120 is supported by, and runs anti-clockwise, as viewed from the front, upon, four similar supporting sprockets, bearingly mounted upon the rear face of the second transverse bulkhead, or second transverse structural member 130, one of which supporting sprockets is keyed to the front end of the forwardly directed shaft 129. As is shown in the Figs. 35-38, each bowling pin conveyor pan 122 consists of a casting, the top of which 15 is concave upwardly transversely, adapted to receive and to hold a bowling pin, disposed horizontally thereupon, with the longitudinal axis of the bowling pin parallel to the longitudinal axis of the bowling pin conveyor pan 122, the ends of which casting are provided with sockets 20 wherein to receive the bowling pin conveyor chain pins 123; and, as has already been stated, the rear end of the casting is provided with a pair of rollers 124. The front end of each bowling pin conveyor pan 122 is provided with a boss 131, which serves to act as a trip for actuating the electric limit switch 132 upon the front face of the second transverse bulkhead, or second transverse structural member 130, with its actuating arm extending rearwardly therethrough.

For the successful operation of the bowling pins magazine conveyor, the bowling pin conveyor pans 122, in operative positions, must always be horizontal and above the bowling pins magazine conveyor chains, 120 and 121, when in either the top row or the bottom row of their positions, as is shown in the Fig. 30. To this end, are 25 provided, at the rear, and on the left-hand and right-hand ends, of the bowling pins magazine mechanism, and mounted upon the front face of the third transverse bulkhead, or third transverse structural member 127, certain cam surface members, with which the rollers 124, bearingly mounted upon the rear ends of the bowling pin conveyor pans 122, engage and disengage, as the bowling pins magazine conveyor chains, 120 and 121, travel along paths substantially trapezoidal in conformation, resulting in the correct positioning of the bowling pin conveyor pans 122 in both rows of their positions 30 shown in the Fig. 30. Thus the interaction of the rollers 124 with the left-hand cam surface plates 133, 134, 135, 136, in the passages of the bowling pin conveyor pans 122 around the forwardly-directed shaft 129, is shown 35 in the Figs. 31-34, while the interaction of the rollers

124 with the right-hand cam surface plates **137**, **138**, **139** in the passages of the bowling pin conveyor pans **122** around the right-hand end of the bowling pins magazine mechanism serves to maintain the bowling pin conveyor pans **122** horizontal, as is obvious from an inspection of the Fig. 30.

As is shown in Figs. 7b, 26, the bowling pin injector mechanism injects, through the end of the bowling pin injector chamber **98**, bowling pins, individually, into the bowling pins magazine mechanism through an aperture in the lower left-hand portion of the third transverse bulkhead, or third transverse structural member **127**. Such injection of bowling pins, individually, into the bowling pins magazine mechanism can be initiated only when: (1), the boss **131** on the front end of a bowling pin conveyor pan **122** is in contact with the actuating arm of the electric limit switch **132**, breaking one set of electrical contacts and bringing to a halt the travel of the bowling pins conveyor chains, **120** and **121**, and making another set of electrical contacts of the electric limit switch **132** in series with one set of electrical contacts of the electric limit switch **96**; and, (2), the head of a bowling pin in the bowling pin chute receiving chamber **93** maintains force-exerting contact with the actuating arm **97** of the electric limit switch **96**. When these two conditions are fulfilled during the operation of the present invention, the bowling pin injector feed arm pusher member **100** is activated, thus displacing, laterally, the bowling pin in the bowling pin receiving chamber **93** into the bowling pin injector chamber **98**, and thus into the path of the then forwardly-moving inclined pusher member **116**, by which the bowling pin is then injected into the bowling pins magazine mechanism; and at the completing of the injecting operation, the head of the injected bowling pin trips the actuating arm of the electric limit switch **140**, renewing the travel of the bowling pins magazine conveyor chains, **120** and **121**; such travel continues until another bowling pin conveyor pan **122** moves into position to receive another bowling pin by injection from the bowling pin injector chamber **98**, and the boss **131** on the front end of that conveyor pan **122** comes into contact with the actuating arm of the electric limit switch **132**, breaking one set of its electrical contacts and again bringing the travel of the bowling pins magazine conveyor chains, **120** and **121**, to a halt; or until each of the ten bowling pin conveyor pans **122** has received a bowling pin injected thereonto, and has moved away from the position of injection directly in front of the bowling pin injector chamber **98**, restoring the bowling pin conveyor pans **122** to the positions occupied by the bowling pin conveyor pans **122**, as shown in the Fig. 30, during the final phase of which, the body of that bowling pin, which was the first of the ten bowling pins that have been injected, has come into actual contact with the actuating arm **141**, positioned directly above the bowling pins magazine mechanism and linked with the electric limit switch **142**, breaking the electrical contacts thereof and bringing the travel of the bowling pins magazine conveyor chains, **120** and **121**, to a halt.

It will be obvious, from an examination of the Fig. 30, that the ten bowling pin conveyor pans **122** are disposed along the front bowling pins magazine conveyor chain **120** in two groups, namely, one group of seven bowling pin conveyor pans **122**, spaced apart a distance equal to two twenty-eighths of the length of the bowling pins magazine conveyor chain **120**, and another group of three bowling pin conveyor pans **122** spaced apart similarly; and with the bowling pin conveyor pan **122** at the end of each group spaced from the bowling pin conveyor pan **122** at the nearer end of the other group of bowling pin conveyor pans **122** by a distance equal to six twenty-eighths of the length of the bowling pins magazine conveyor chains, **120** and **121**, is intermittent in its nature, each unit of travel being two twenty-eighths of the total length of each of the bowling pins magazine conveyor chains, **120** and **121**; during each unit of travel, the bowl-

ing pins magazine conveyor chains travel, acceleratingly, for one twenty-eighth of the length of either of the bowling pins magazine conveyor chains, **120** and **121**; and then, deceleratingly, for the next one twenty-eighth of the length of either of the bowling pins magazine conveyor chains, **120** and **121**.

The bowling pins charging mechanism

As is shown in the Figs. 7b, 8b, 35, 39, 40, 41, 42, 10 the bowling pins charging mechanism comprises a horizontally disposed upper cross member **150**, provided with the seven pusher members **151**, and provided with, and supported by, the two bearing arms **152** in travelling upon the two horizontally disposed upper slide rods **153**, 15 secured directly to the second transverse bulkhead, or second transverse structural member **130**, and, by the supporting brackets **154**, to the third transverse bulkhead, or third transverse structural member **127**; a horizontally disposed lower cross member **155**, parallel to, and shorter than, the upper horizontal cross member **150**, and provided with the three pusher members **156** (one of which is shown in the Fig. 35, but all of which are hidden in the Fig. 39); and a U-shaped member **157**, united with the horizontally disposed upper cross member **150**, and with the horizontally disposed lower cross member **155**, to form an integral structure, namely, the bowling pins charging structure, whose U-shaped member **157** lies in a plane perpendicular to the planes of the horizontally disposed upper and lower cross members, **150** and **155**. 20 At the center of the bottom portion of the U, the bowling pins charging structure is provided with an L-shaped arm **158**, (a part of the lower (horizontal) part of which is cut off), rigidly secured thereto, and with an aperture, 25 extending through the U-shaped member **157** and the L-shaped arm **158** and provided with a sleeve **159** that serves as a bearing for the travel of the bowling pins charging structure upon the horizontally disposed lower slide rod **160**, secured to the third transverse bulkhead, 30 or third transverse structural member **127**, and to the supporting member **161**, secured to the floor of the box-like structure. Thus, the bowling pins charging structure may be reciprocated upon the two horizontally-disposed upper slide rods **153** and the horizontally disposed lower slide rod **160**, its rearmost position being attained when 35 the sleeve **159** comes into contact with the top of the supporting member **161**, secured to the floor of the box-like structure.

Affixed to the bottom of the L-shaped arm **158** are two chain pin engaging bars, **162** and **163**, the right-hand chain pin engaging bar **162** being spur-like in conformation and projecting beyond the edge of the L-shaped arm **158**. The two chain pin engaging bars, **162** and **163**, are positioned over a portion of the serpentine chain drive **115**, 40 here disposed in a conformation shaped like a U with rounded ends, upon sprocket wheels, and driven at a speed that varies periodically from approximately zero to a maximum to approximately zero. When engaged by a chain pin **114**, carried by the serpentine chain drive **115**, the right-hand chain pin engaging bar **162** serves as a cam plate for the advancing of the bowling pins charging structure into and within the bowling pins magazine mechanism, and the left-hand chain pin engaging bar **163** serves as a cam plate for the withdrawing of the bowling pins charging structure within and out of the bowling pins magazine mechanism and back to its rearmost position, before the chain pin **114** and the left hand chain pin engaging bar **163** become disengaged. While the disengagement of the chain pin **114** and the left-hand chain pin engaging bar **163** occurs, and can occur, when and 45 only when the bowling pins charging structure is in its rearmost position, as is shown in Fig. 39, the engagement of a chain pin **114** by and with the right-hand chain pin engaging bar **162** can never occur when the bowling pins charging structure is in its rearmost position, as is shown in the Fig. 39; in such a contingency the chain

pin 114 passes in front of, and without making contact with, the right-hand chain pin engaging bar 162, as is shown in the Fig. 39: the engagement of a chain pin 114 by and with the right-hand chain pin engaging bar 162 occurs, and can occur, when, and only when, the bowling pins charging structure is advanced a short distance, beyond, and in front of, its rearmost position, as is shown in the Fig. 41. Hence, for effecting such advancing, when desired, of the bowling pins charging structure a short distance beyond, and in front of, its rearmost position, there is provided a pusher member 164, solenoid actuated, and so positioned that it can impact the bowling pins charging structure, the solenoid being activated through electrical control means in a manner to be described later, which electrical control means includes the electric limit switch 165, mounted upon one of the support brackets 154 and so positioned that its actuating arm will be actuated by contact with one of the bearing arms 152 in its rearmost position.

The purposes and the functions of the bowling pins charging mechanism are to effect, simultaneously, the translating, in the direction of their longitudinal axes, of ten bowling pins, orientated heads foremost along the direction of the proposed translations, and positioned in space in a predetermined spatial arrangement, or pattern, with their longitudinal axes mutually parallel, out of a bowling pins magazine mechanism and into a bowling pins carrying structure, while preserving the predetermined spatial arrangement, or pattern, under conditions of demand imposed by other mechanisms cooperating therewith.

The bowling pins carrying and sweeping mechanism

As is shown in the Figs. 5, 6, 7a, 8b, 43 44, 45, the bowling pins carrying and sweeping mechanism comprises an integral structure 170, hereinafter called the bowling pins carrying and sweeping structure, in length (largest dimension) substantially equal to the width of a bowling alley bed, having upon each of its ends a doubly forked dog 171, each for engagement with a double chain pin 172 (see Fig. 11), carried by the forward-and-reverse chain drives 173, so that through such engagements of the two doubly-forked dogs 171 and double chain pins carried by the two forward-and-reverse chain drives 173, the bowling pins carrying and sweeping structure 170 is elevated and erected out of the bowling pins carrying and sweeping structure receiving chamber 174, as is shown in the Fig. 5, is moved, when and while erect, upon sets of rollers 175 that travel in the channels 176, affixed to the bottom edge portions of the hinged bowling pins spots plates 177, forward and backward, over the hinged bowling pins spots plates 177, as is shown in the Fig. 8b, and is de-erected and lowered into the bowling pins carrying and sweeping structure receiving chamber 174, the rollers 175 then travelling in the channels 178, affixed to the second transverse bulkhead, or second transverse structural member 130, these operations being preceded by the tilting of the hinged bowling alley surface plates 179 and followed by the detilting of the hinged bowling alley surface plates 179, the tilting and the detilting of the hinged bowling alley surface plates 179 being effectuatable by the two single chain pins 180, carried by the forward-and-reverse chain drives 173, as will be described subsequently.

The bowling pins carrying and sweeping structure 170 is provided with four one-bowling-pin chambers 181, U-shaped in horizontal cross section (when the bowling pins carrying and sweeping structure 170 is erect, as is shown in the Fig. 43), for receiving and holding, individually, the bowling pins 7, 4, 6, 10, and three two-bowling-pins-chambers 182, U-shaped in horizontal cross section (when the bowling pins carrying and sweeping structure 170 is erect, as is shown in the Fig. 43), for receiving and holding in pairs, tandemwise, the bowling pins, 8, 2; 5, 1; 9, 3.

Each of the one-bowling-pin chambers 181 is shaped to

receive, when the bowling pins carrying and sweeping structure 170 is in the horizontal position in the bowling pins carrying and sweeping structure receiving chamber 174, a bowling pin, by translation, head foremost, from the bowling pins magazine mechanism, through the operation of the bowling pins charging mechanism, and is provided with plates, hingedly mounted along longitudinal edges upon the bowling pins carrying and sweeping structure 170 and spring-loaded, constituting for the one-bowling-pin-chamber 181 outwardly-opening doors, 183 and 184, one of which, 183, carries a finger 185 for making and maintaining contact with the head of a bowling pin, and both of which, 183 and 184, serve as bowling pins impingement plates in the sweeping operation of the bowling pins carrying and sweeping mechanism.

Each of the two-bowling-pins-chambers 182 is shaped to receive, when the bowling pins carrying and sweeping structure 170 is in the horizontal position, two bowling pins, by translation, heads foremost, from the bowling pins magazine mechanism, through the operation of the bowling pins charging mechanism, and is provided with right-hand and left-hand spring loaded articulated structures, transforming the two-bowling-pins-chamber 182 into an inner bowling pin chamber 186 and an outer bowling pin chamber 187, comprising plates 188, hingedly mounted along longitudinal edges, upon the bowling pins carrying and sweeping structure 170, constituting, for the inner bowling pin chamber 186, formed by the rear wall and the rear portions of the lateral walls of the two-bowling-pins-chamber 182, outwardly opening doors, each of which carries a finger 189 for making and maintaining contact with the head of a bowling pin within the inner bowling pin chamber 186, and arcuate plates 190, hingedly connected, along longitudinal edges, to the other longitudinal edges of the plates 188, the hinged connections between the arcuate plates 190 and the plates 188 being spring-loaded, and provided at the other longitudinal edges, and near the bottoms of the arcuate plates, 190, with brackets 191, upon which are bearingly mounted the rollers 192 for travel upon the interior surfaces of the bowling pins carrying and sweeping structure 170, constituting, for the outer bowling pin chamber 187, the rear portion thereof; while plates, hingedly mounted along longitudinal edges, upon the bowling pins carrying and sweeping structure 170 and spring-loaded, constituting for the outer bowling pin chamber, outwardly opening doors, 183 and 184, one of which, 183, carries a finger 185 for making and maintaining contact with the head of the bowling pin within the outer bowling pin chamber 187, and both of which form, with the arcuate plates 190 and the forward portions of the lateral walls of the two-bowling-pins-chamber, the outer bowling pin chamber 187, and serve as bowling pin impingement plates in the sweeping operation of the bowling pins carrying and sweeping mechanism. The one-bowling-pin-chambers 181 and the two-bowling-pin-chambers 182 hold, loosely and vertically, when the bowling pins carrying and sweeping structure 170 is in vertical position over the hinged bowling pins spots plates 177, as is shown in the Fig. 8b, the bowling pins during the rearward movement, over the hinged bowling pins spots plates 177, of the bowling pins carrying and sweeping structure 170, during which rearward movement of the bowling pins carrying and sweeping structure 170 loose bowling pins and bowling balls, lying upon the hinged bowling pins spots plates 177, are swept from the hinged bowling pins spots plates 177 into the pit. During the forward movement of the bowling pins carrying and sweeping structure 170, the spring-loaded outwardly-opening doors, 183 and 184, and the spring-loaded plates 188 serve to restrain the bowling pins immediately in front of them from escape until such time when the forward movement of the bowling pins, individually, is arrested by energization of appropriate bowling pin traction

magnets 193, arranged in the usual triangular arrangement of bowling pins spots and embedded in the hinged bowling pins spots plates 177, by sequential actuations of the electric limit switches 197, 198, 199, 200, governing the energization of bowling pin traction magnets 193, over which bowling pins are immediately positioned; whereupon the energized bowling pin traction magnets 193, acting upon armatures 194, embedded in the bases of bowling pins positioned immediately over the energized bowling pin traction magnets 193, arrest the bowling pins against further movement, laterally, and the bowling pins, thus transfixed, be they in the one-bowling-pin-chambers 181, or in the outer chambers 187 of the two-bowling-pin-chambers 182, or be they in the inner bowling pin chambers 186 of the two-bowling-pin-chambers 182, escape through the spring-loaded doors 183, 184, or through the spring-loaded plates 188 and the spring-loaded doors 183, 184, respectively. As will be obvious from the Fig. 5, after the bowling pins have passed through the spring-loaded doors 183, 184, or through the spring-loaded plates 188 and the spring-loaded doors 183, 184, respectively, these spring-loaded structures return to their spring-loaded positions, and each bowling pin remains, held positioned upon a bowling pin spot by a bowling pin traction magnet 193, so that upon the return of the bowling pins carrying and sweeping structure 170 into the bowling pins carrying and sweeping structure receiving chamber 174, all ten bowling pins are left standing in predetermined positions upon the hinged bowling pins spots plates 177, after which return, the bowling pin traction magnets 193 are de-energized, as will be explained subsequently.

As constructions alternative to the bowling pin traction magnets 193, for utilization in the setting of bowling pins upon the hinged bowling pins spots plates 177 by the bowling pins carrying and sweeping mechanism, and in the clearing of "deadwood" from the hinged bowling pins spots plates 177 and the hinged bowling alley surface plates 179, solenoid-actuated bowling pin spotter pegs 195, as is shown in the Fig. 47, may be employed, if each bowling pin is provided with a suitable cavity 196 in the base thereof, wherein to receive the bowling pin spotter peg 195.

The hinged bowling alley surface plates

As is shown in the Figs. 1, 2, 4, 6, 8a, 12, 13, the hinged bowling alley surface plates 179, located immediately to the rear of the bowling alley bed, proper, 11, and serving as lids over the bowling pins carrying and sweeping structure receiving chamber 174, consist of two plates, the widths of which are not greatly unlike, and, summed, are substantially equal to the width of the bowling alley bed, proper, 11. The hinged bowling alley surface plates 179 are hingedly connected along their longitudinal edges to the first transverse bulkhead, or first transverse structural member 201, and the lateral structural members, 202 and 203, respectively, which, together with the second transverse bulkhead, or second transverse structural member 130, form a frame. The hinged bowling alley surface plates 179 are each provided with a hinged bowling alley surface plate tilting and detilting mechanism, which comprises a linking member 204, bearingly connected at one of its ends, through a universal joint 205, to the underside of the hinged bowling alley surface plate 179 (in the Figs. 12 and 13, the right-hand hinged bowling alley surface plate 179), and bearingly connected at the other of its ends, through a universal joint 206, to the end of one prong 207 of a forked crank arm 208, bearingly mounted upon the drive shaft 209 and provided at the end of the other prong 210 thereof with a wide notch between the two driving lugs 211 and 212, wherein is receivable, for rotation of the forked crank arm 208, clockwise and counter clockwise, a single chain pin 180, carried by the forward-and-reverse chain drive 173, trav-

eling upon the sprocket wheel 213, adjacent to the prong 210 and secured to the drive shaft 209; while a stop member 214, secured to the inner face of the lateral structural member, 202 or 203, delimits the rotation of the forked crank arm 208, when the hinged bowling alley surface plate 179 has been completely tilted.

Intermediate between the two prongs 207 and 210, of the forked crank arms 208 are located electric limit switch actuating lugs. The electric limit switch actuating lug 215 is so positioned upon the right-hand forked crank arm 208 as to actuate, and thereafter to maintain actuated, the electric limit switch 216, when the hinged bowling alley surface plates are in the final stages of detilting. The electric limit switch actuating lug 217 is so positioned upon the left-hand forked crank arm 208 as to actuate the electric limit switch 218 when the hinged bowling alley surface plates 179 attain the half-tilted positions assumed by them in the "deadwood clearing" operation.

The actuation of the electric limit switch 216 brings the travel of the forward-and-reverse chain drive 173 to a halt and de-energizes the bowling pin traction magnets 193, while the actuation of the electric limit switch 218 causes reversal of travel of the forward-and-reverse chain drive 173 but only in the "deadwood clearing" operation.

As is shown in the Figs. 8a and 9, the bowling alley surface plates 179 are also provided, each upon its underside, with a portion of latching mechanism for latching together (slidingly) each hinged bowling alley surface plate 179 and the hinged bowling pins spots plate 177 adjacent thereto, which comprises a spring-return bolt 219, actuated by a solenoid 220, for engaging in a slotted structure 221 positioned upon the underside of the hinged bowling pins spots plate 177 adjacent to that hinged bowling alley surface plate 179.

The hinged bowling pins spots plates

As is shown in the Figs. 1, 2, 4, 5, 8b, the hinged bowling pins, spots plates 177, located adjacent to, and in the rear of, the hinged bowling alley surface plates 179, and serving as lids of that portion of the box-like structure that contains the bowling pins and bowling balls handling mechanisms, consist of two plates, the width of each of which is substantially equal to the width of the bowling alley surface plate 179, adjacent thereto, and the widths of both of which summed, are substantially equal to the width of the bowling alley bed, proper, 11. The hinged bowling pins spots plates 177 are bearingly mounted, at their outer two corners, upon the second transverse bulkhead, or second transverse structural member 130 and upon the rear (fourth) transverse bulkhead, or fourth transverse structural member 48, and each hinged bowling pins spots plates 177 is provided, along its bottom edge portion, with a channel 176, wherein the rollers 175 travel. As is shown in the Fig. 9, the hinged bowling pins spots plates 177 are provided, each upon its underside, with a portion of latching mechanism, for latching together each hinged bowling pins spots plate 177 and the hinged bowling alley surface plate 179 adjacent thereto, which comprises a slotted structure 221 for receiving in engagement therewith a spring return bolt 219, actuated by a solenoid 220, positioned upon the underside of the hinged bowling alley surface plate 179 adjacent to the hinged bowling pins spots plate 177. When the latching means, 219 and 221, are engaged, each of the hinged bowling alley surface plate tilting and detilting mechanisms tilts and detilts the thus-united ensemble of hinged bowling alley surface plate 179 and hinged bowling pins spots plate 177.

The left-hand hinged bowling pins spots plate 177 is provided with six bowling pin traction magnets 193 and the right-hand hinged bowling pins spots plate 177 is provided with four bowling pin traction magnets 193, the bowling pin traction magnets 193 in any given row of bowling pin traction magnets 193, perpendicular to the

axis of the bowling alley (e.g., 7, 8, 9, 10; 4, 5, 6; 2, 3; 1), being in a common circuit: the four such common circuits are successively energized, in the setting of the bowling pins upon the hinged bowling pins spots plates 177, by the actuations of the four electric limit switches 197, 198, 199, 200, positioned upon the left-hand lateral supporting member 222, by one of the doubly-forked dogs 171 of the bowling pins carrying and sweeping structure 179, in its return travel over the bowling pins spots plates 177. The ten bowling pin traction magnets 193, as an entity, are provided with a second circuit for their energization for, and during, the operation of clearing "deadwood" from the hinged bowling pins spots plates 177 and the hinged bowling alley surface plates 179, as will be described subsequently. As has already been stated, as constructions alternative to the bowling pin traction magnets 193, for utilization in the setting of bowling pins upon the bowling pins spots plates 177 by the bowling pins carrying and sweeping mechanism, and in the clearing of "deadwood" from the hinged bowling pins spots plates 177 and the hinged bowling alley surface plates 179, solenoid-actuated bowling pin spotter pegs 195, receivable in cavities 196, provided in the bases of the bowling pins, may be employed, utilizing the same electrical circuits, and the same electrical control means for governing the actuations of such circuits, as are employed in the utilization of the bowling pin traction magnets.

As is shown in the Figs. 5, 8a, 7b, mounted upon the first transverse bulkhead, or first transverse structural member 201, is a hold-down magnet 223 with three poles, so positioned that when the hinged bowling alley surface plates 179 are down in their wholly detilted positions, they rest upon the hold-down magnet 223, which serves as a stop member, and which, when energized, serves also as a means for holding the hinged bowling alley surface plates 179 fixed with respect to rotatory movement.

As is shown in the Fig. 7b, mounted upon a supporting member affixed to the floor of the box-like structure is a hold-down magnet 224 with three poles, so positioned that when the hinged bowling pins spots plates 177 are down in their wholly detilted positions, they rest upon the hold-down magnet 224, which serves as a stop member, and which, when energized, serves also as a means for holding the hinged bowling pins spots plates 177 fixed with respect to rotatory movement.

The purpose and the function of the hold-down magnets, 223 and 224, is to insure that the hinged bowling alley surface plates 179 and the hinged bowling pins spots plates 177 will present a level bowling surface in the same plane as, and substantially continuous with, the plane of the surface of the bowling alley bed, proper 11.

The ball track, the ball guards, and the ball elevating mechanism

As is shown in the Figs. 7a and 7b, the ball track 83, originating at the bowling pins and bowling balls separating mechanisms, passes under the right-hand bowling alley gutter vibratory conveyor and through the third, second and first transverse bulkheads, or third, second and first transverse structural members, 127, 130, and 201, respectively; then, making a right angle turn, passes, in the present instance, in front of the first transverse bulkhead, or first transverse structural member 201, and under the forward end portion of the left-hand bowling alley gutter vibratory conveyor, to the ball elevating mechanism, into which extends one rail of the ball track 83, provided with the protuberance 230 for the purpose of deflecting bowling balls forwardly therefrom, the ball elevating mechanism being positioned on the left-hand side of the left-hand bowling alley gutter 12. Also shown in the Fig. 7a are the two ball guards 231, hingedly mounted upon, and supported by, the first transverse bulkhead, or first transverse structural member 201, and

which, when in their horizontal positions, substantially cover, as hinged lids, the space between the front wall of the box-like structure and the first transverse bulkhead, or first transverse structural member 201, where-through, in the present instance, the ball track 83 passes. The ball guards 231, spring-loaded, are held in such horizontal positions by the hinged bowling alley surface plates 179 and their hold-down magnet 223, when the hinged bowling alley surface plates 179 are in their horizontal detilted positions: as and when the hinged bowling alley surface plates 179 are tilted, the ball guards 231 automatically assume their positions of maximum tilt, as is shown in Figs. 4, 5, 6, 8a, 9; and in their positions of maximum tilt, they serve to deflect onto the ball track 83, extending below the ball guards 231, all bowling balls travelling rearwardly over the surface of the bowling alley bed, proper, 11, when and while the hinged bowling alley surface plates 179, or the hinged bowling alley surface plates 179 and the hinged bowling pins spots plates 177, latched together, are tilted. The purpose and the function of the ball guards 231 are to protect against possible injury, incurable through bowling balls bowed when and while the hinged bowling alley surface plates 179, or the hinged bowling alley surface plates 179 and the hinged bowling pins spots plates 177, are tilted, the bowling pins and bowling balls handling mechanisms then exposed.

As is shown in Figs. 7a, 8a, the bowling ball elevating mechanism, to which bowling balls are delivered by the ball track 83, comprises the arcuate conduit, defined by the upper arcuate wall 232 and the lower arcuate wall 233, wherein the bowling balls are received, and come into yielding contact with the rotatable peripherally pneumatic member 234, driven through frictional contact with the drive wheel 235 mounted upon the shaft of the motor 236, which imparts to each bowling ball rotatory energy sufficient to impel the bowling ball up through the arcuate conduit and, as is shown in the Fig. 4, onto the ball return 17, whereby the bowling ball is returned to the bowler.

Power means

Exclusive of the motor 236 of the bowling ball elevating mechanism, there are two power means utilized in the present invention, namely, the power means for driving the forward-and-reverse chain drives 173 and the power means for driving all other of the bowling pins and bowling balls handling mechanisms.

The power means for driving the forward-and-reverse chain drives 173 is, in the present instance, a three-phase reversing gear motor 240 which drives, through the chain 241, the drive shaft 209, bearingly mounted in the lateral structural member 202 and on the first transverse bulkhead, or first transverse structural member 201, and carrying, keyed thereto, sprockets 213, upon which, together with the sprockets 242 and the ancillary sprockets, shown in the Figs. 8a, 8b, are disposed the forward-and-reverse chain drives 173, each carrying the double chain pin 172 and the single chain pin 180, so spaced from the double chain pin 172, that, in forward travel of the forward-and-reverse chain drive 173, the single chain pin 180 becomes engaged, and thereafter disengaged, with the driving lug 211 before the double-chain pin 172 becomes engaged with the doubly forked dog 171, thus insuring that the hinged bowling alley surface plates 179 are wholly tilted before the bowling pins carrying and sweeping structure 179 begins to emerge from the bowling pins carrying and sweeping structure receiving chamber 174.

The power means for driving all other of the bowling pins and bowling balls handling mechanisms is, in the present instance, a unidirectional gear motor 250, one shaft 251 of whose gear box drives directly the first endless chain lug conveyor 79 and the second endless chain lug conveyor 85, and the other shaft of whose gear

box drives, through sprockets and a drive chain 252, the variable speed, or quasi-harmonic, drive, which, in turn, drives through spiral gears the serpentine chain drive 115, and drives through the one-revolution clutch, actuated by the solenoid 253, and the drive chain and suitable sprockets, the bowling pins magazine mechanism: the variable-speed, or quasi-harmonic, drive, the spiral gears, and the one-revolution clutch and the solenoid 253 therefor, are contained by and in the housing 254 shown in the Figs. 7b and 8b, while the solenoid 253 is shown only in the wiring diagram of the Fig. 54. Since the variable speed, or quasi-harmonic, drives and the one-revolution clutches are devices well known in the art, detailed description of these devices are omitted. The character of the travel imparted by the variable speed drive to the serpentine chain drive 115 and to the bowling pins magazine conveyor chains, 120 and 121, through the drive chain 128 and the one-revolution clutch, when engaged, is quasi-harmonic i.e. it is intermittent or periodical: during each period of travel, the serpentine chain drive 115 and the bowling pins magazine conveyor chains, 120 and 121, travel, first, acceleratingly, at speeds varying continuously from approximately zero to maximum speeds, and thereafter deceleratingly, from speeds varying continuously from maximum speeds to approximately zero. By the utilization of such variable speed drive, smoothness of operation is attained in the functionings of the third (storage) chain lug conveyor, the bowling pin injector mechanism, and the bowling pins charging mechanism, all of which mechanisms are driven by the serpentine chain drive 115, disposed upon sprockets in a horizontal plane; and greater maximum speeds of operation of the bowling pins magazine conveyor chains, 120 and 121, and consequently a greater number of periods of operation per unit of time, are attainable without incurring dislodgement of bowling pins from the bowling pins conveyor pans 122, such as would be incurred were the speeds of the bowling pins magazine conveyor chains, 120 and 121, altered abruptly.

Alternative embodiments of the bowling pins and bowling balls separating and orientating mechanisms

Reference has been made to embodiments of the bowling pins and bowling balls separating and orientating mechanisms alternative to the preferred embodiment heretofore described and illustrated; and two such embodiments, utilizing the same general principles of construction and operation, are hereinafter described and illustrated.

In both embodiments, utilization is made of the pocket-like structure into which are discharged, downwardly from, and off of, the prow 47 of the bowling alley pit vibratory conveyor, individually, bowling balls and bowling pins, indiscriminately base foremost and head foremost.

As is shown in Figs. 48, 49, 50, in the first of the two alternative embodiments of the bowling pins and bowling balls separating and orientating mechanisms, the pocket-like structure constitutes the lower end portion of a sloping conduit, formed by the floor 73 and the wall 72 and the wall-like member 77, through which travel the lugs 78, mounted upon, projecting from, and perpendicular to the vertical plane of travel of, the rear (first) endless chain lug conveyor 79, a lug 78 serving to impel, individually, either a bowling ball or a bowling pin, indiscriminately base foremost or head foremost, upwardly, to the summit of the floor 73, until it is discharged, downwardly, and onto, a floor 260, slightly inclined downwardly, beyond the rear (first) endless chain lug conveyor 79, wherefrom a bowling ball is discharged, by gravity, downwardly, onto a ball track 83, and whereupon a bowling pin remains, disposed in either of the two positions, substantially as is shown in broken lines in the Figs. 48, 50, and held thus by frictional forces on the floor 260, slightly inclined downwardly.

Above the rear edge of the floor 260, slightly inclined downwardly, is positioned a bowling pin impacting mechanism 261, which comprises a spring-return, solenoid-actuated, pusher member, and above the front edge of the floor 260, slightly inclined downwardly, are positioned two bowling pin orientating members 262, in opposition to the bowling pin impacting mechanism 261, spaced apart a distance intermediate the greatest diameter, and the length, of a bowling pin, and flanking the passage interconnecting the conduits of the first and the second endless chain lug conveyors, 79 and 85, respectively. Upon the floor of the box-like structure is so positioned the electric limit switch 263, controlling the energization of the bowling pin impacting mechanism 261 and actuatable by the lugs 78 of the rear (first) endless chain lug conveyor 79, and along the rear (first) endless chain lug conveyor 79 are so distributed the lugs 78, that the bowling pins impacting mechanism 261 is energized at a brief interval of time after the time that either a bowling ball or a bowling pin, indiscriminately base foremost or head foremost, has been discharged, downwardly, and onto, the floor 260, slightly inclined downwardly, so that a bowling ball can freely roll past the bowling pin impacting mechanism 261 before its energization, but a bowling pin will invariably be subjected to impact by the bowling pin impacting mechanism 261. Namely, the bowling pin impacting mechanism 261 impacts the belly of the bowling pin, disposed in either of the two positions, as shown in broken lines in the Figs. 48, 50, thus projecting, laterally, the bowling pin, between, and past, the two orientating members 262, with one of which the head and/or the neck of the bowling pin comes into contact, so that the bowling pin is discharged, base foremost, onto the second endless chain lug conveyor 85, which discharges, onto the third (storage) endless chain lug conveyor 90, the bowling pin, orientated head foremost in the direction of its possible travel thereon. Thereafter, the bowling pin is subjected to bowling pins and bowling balls handling mechanisms identical with the bowling pins and bowling balls handling mechanisms comprised in combination with the preferred embodiment of the bowling pins and bowling balls separating and orientating mechanisms, save that the first endless chain lug conveyor 79 is not driven directly by the shaft 251 of the unidirectional gear motor 250, but is driven by the shaft 251 through sprockets, the chain of the second endless chain lug conveyor 85, and the drive chain 264.

As is shown in the Figs. 51, 52, 53, in the second of the two alternative embodiments of the bowling pins and bowling balls separating and orientating mechanisms, the pocket-like structure constitutes the lower end portion of a sloping conduit, formed by the floor 73 and the wall 72 and the wall-like member 77, through which travel the lugs 78, mounted upon, projecting from, and perpendicular to the vertical plane of travel of, the rear (first) endless chain lug conveyor 79, a lug 78 serving to impel, individually, either a bowling ball, or a bowling pin, indiscriminately base foremost or head foremost, upwardly, toward the summit of the floor 73, before the attaining of which it is discharged, by gravity, through the cooperating actions of the lug 78 and the arcuate portion 80 of the wall-like member 77, downwardly, and onto, the two parallel belts 270, constituting a dual belt conveyor, whose upper plane of travel is inclined downwardly in the direction opposite to the direction of their travel, and which travel above, and parallel to, a first baffle member 271, positioned at the receiving end of the dual belt conveyor and below, and substantially parallel to, a second baffle member 272, positioned at the discharging end of the dual belt conveyor: the two parallel belts are driven by the pulley 273, mounted upon the drive shaft 251 of the unidirectional gear motor 250 and run upon the pulley 274, bearingly mounted upon the supporting member 275, affixed to the floor of the box-like

structure, and are spaced apart, and maintained spaced apart, a distance intermediate the greatest diameter of the head, and the greatest diameter of the belly, of a bowling pin. When a bowling ball is discharged, by gravity, downwardly, and onto, the dual belt conveyor, the bowling ball rolls upon the two parallel belts 270 in the direction opposite to the direction of their travel, and is discharged, by gravity, downwardly, and onto, a ball track 83; whereas, when a bowling pin is discharged, by gravity, downwardly, and onto, the dual belt conveyor, the bowling pin, in either of the two positions, as shown by broken lines in the Fig. 51, is carried, upwardly, by the two parallel belts 270 of the dual belt conveyor. If the bowling pin is discharged downwardly, and onto the dual belt conveyor, orientated head foremost in the direction of its possible travel, the bowling pin, suspended by, and upon, the two parallel belts 270 of the dual belt conveyor, with its head and a portion of its neck situated below the upper plane of travel of the two parallel belts 270 of the dual belt conveyor (before and after the bowling pin has been carried beyond contact with the first baffle member 271), is carried upwardly, and the head of the bowling pin comes into contact with the ancillary flat belt conveyor, whose belt 276 runs upon the pulley 274, interposed between the two parallel belts 270 of the dual belt conveyor, and upon the pulley 277, bearingly mounted upon the supporting member 278, affixed to the floor of the box-like structure; whereupon the head of the bowling pin is elevated and the bowling pin, orientated head foremost in the direction of its travel, is discharged into the rotary conveyor 279, wherein such orientation is preserved through the cooperating actions of the shaft 280 of the rotary conveyor 279, the extension, into the rotary conveyor 279, of the wall 84, and the counterclockwise rotation, as shown in the Fig. 51, of the rotary conveyor 279, from which the bowling pin is discharged, orientated head foremost in the direction of its travel, onto the third (storage) endless chain lug conveyor 90. But if the bowling pin is discharged downwardly, and onto, the dual belt conveyor, orientated base foremost in the direction of its possible travel, the bowling pin suspended by, and upon, the two parallel belts 270 of the dual belt conveyor, with its head and a portion of its neck situated below the upper plane of travel of the two parallel belts 270 of the dual belt conveyor (before, and up to the time that, the bowling pin has been carried out of contact with the first baffle member 271), is compelled, by the forces reacting thereon, to rotate about a transverse axis, more or less than one complete rotation (clockwise, if the direction of travel of the two parallel belts appears to be from right to left; and conversely), dependent upon the inclination and the speed of the two parallel belts 270 of the dual belt conveyor; but, by the cooperating actions of the flat belt 276, of the ancillary flat belt conveyor and the second baffle member 272, positioned above, and substantially parallel to, the upper plane of travel of the two parallel belts 270 of the dual belt conveyor, the bowling pin, discharged downwardly, and onto, the dual belt conveyor, originally orientated base foremost in the direction of its possible travel, is discharged, into the rotary conveyor 279, orientated head foremost in the direction of its travel, wherein such orientation is preserved through the cooperating actions of the shaft 280 of the rotary conveyor 279, the extension, into the rotary conveyor 279, of the wall 84, and the counterclockwise rotation, as shown in the Fig. 51, of the rotary conveyor 279, from which the bowling pin is discharged, orientated head foremost in the direction of its travel, onto the third (storage) endless chain lug conveyor 90. Thereafter, the bowling pin is subjected to bowling pins and bowling balls handling mechanisms identical with the bowling pins and bowling balls handling mechanism comprised in combination with the preferred embodiment of the bowling pins and bowling balls separating and orientating mechanisms, save that

the rotary conveyor is driven by the serpentine chain drive 115, through pulleys, twisted belt, and the chain of the third (storage) endless chain lug conveyor 90.

Control and power circuits

In the Figs. 54 and 55 are shown units of the control and the power circuits, including details pertinent to such units, of a right-hand bowling pin setting machine, i.e., an installed bowling pin setting machine, with its ball elevating mechanism positioned on the right-hand side of the bowling pin setting machine, comprising, in combination, in addition to the connecting wires shown in the Fig. 54; the switch 300 for disconnecting the three-phase power circuit to the bowling pin setting machine; the switch 301 for disconnecting the signal-phase power circuit to the ball elevating mechanism; the switch 302 for disconnecting the bowling alley lighting circuit, common to two adjacent bowling alleys, from the 110-volt-24-volt control circuit transformer 303, supplying alternating current for the control circuit A of the right-hand bowling pin setting machine; the switch 304 for disconnecting the bowling alley lighting circuit from the 110-volt-24-volt control circuit transformer 305, supplying current to the control circuit of the left-hand bowling pin setting machine adjacent to the right-hand bowling pin setting machine, the wiring diagram of which, as has been said, is shown in the Fig. 54; the main contactor 306 whose contacts become closed upon energization of its operating coil by 24-volt alternating current from the control circuit A; the ball elevating mechanism motor contactor 307, whose contacts become closed upon energization of its operating coil by current either through the leads R, connected and X in the control circuit of a left-hand bowling pin setting machine, or through the leads X—R, from a right-hand bowling pin setting machine, and the normally open contacts of the ball elevating mechanism relay 308, which normally open contacts become closed upon energization of the operating coil of the ball elevating mechanism relay 308 by current through the leads X—Y from the control circuit A; the transformer and rectifier unit 309, which comprises, as is shown in detail in the Fig. 55, the Scott-connected type of three phase-four phase, 220-volt-28-volt transformers 310, the fuses 311, the rectifiers 312, and the choke 313 which yields full-wave rectified direct current of a potential of approximately 24 volts to the power circuit B and half-wave interrupted direct current of a potential of approximately 24 volts to the vibratory conveyor magnet circuits C, C, the center lead being common to both vibratory conveyor magnet circuits; the three-phase reversing gear motor reversing contactor 314, shown in the Fig. 54, with its "forward" operating coil at the bottom, and its "reverse" operating coil at the top, of the diagrammatic representation thereof; the bowling pin traction magnets 320, 321, 322, 323, whose contacts are normally opened and, when closed, supply operating direct current from the power circuit B to the bowling pin traction magnets 193 in the bowling pins positions 1; 2, 3; 4, 5, 6; and 7, 8, 9, 10; respectively; the bowling pins slave relay 324 and the bowling pins carrying and sweeping mechanism reversing relay 325; and four latch-in relays (by which term, "latch-in relays," is meant relays the energization of whose operating coils causes the closing of contacts normally opened and the opening of contacts normally closed; and the normally opened contacts thus closed and the normally closed contacts thus opened are maintained closed and opened, respectively, by latches, themselves actuated by detaching coils, until such time when alternating current is applied to the detaching coils), the latch-in relays being the "deadwood clearing" cycle latch-in relay 330, the bowling pin setting cycle latch-in relay 331, the charger sequence latch-in relay 332, and the bowling pins magazine latch-in relay 333. Also shown in the wiring diagram of the Fig. 54 are five push buttons, the push buttons being: the normally

opened three-phase reversing motor starting service push button 340; the normally opened, normally closed, set cycle service push button 341; the normally opened, normally closed, "deadwood clearing" cycle service push button 342; the normally opened, normally closed, set cycle bowler's push button 343; and the normally opened, normally closed "deadwood clearing" cycle bowler's push button 344; the last two designated push buttons are located at the bowler's position to enable the bowler to initiate the operation of the bowling pin setting machine in the setting of bowling pins upon the hinged bowling pins spots plates 177 and to initiate the operation of the bowling pin setting machine in the "clearing of deadwood" from the hinged bowling pins spots plates 177 and the hinged bowling alley surface plates 179, respectively; while the first three designated push buttons are located adjacent to the bowling pin setting machine for the purposes of operating the bowling pin setting machine during servicing or testing. The single pole double throw switches, 345 and 346, are provided, adjacent to the bowling pin setting machine, to determine which set of push buttons will control the initiation of cycles of operation. The signal light 350 is provided, at the bowler's position, to indicate to the bowler when the control circuits are so set as to enable the bowler to initiate a bowling pins setting cycle, the signal light 350 being lit during occasions when the bowling pins setting cycle may be initiated by the bowler.

In the wiring diagram shown in the Fig. 54, all relays, latch-in relays, and contactors are shown in their normal positions, i.e. with no current impressed upon their operating coils, and, in the instances of the latch-in relays, after their detachments; and the various electric limit switches are shown in their normal positions, i.e., with their actuating arms unstressed, except that the electric limit switch 216 is shown in the actuated position assumed when the hinged bowling alley surface plates 179 are horizontal and wholly detilted, and except that the electric limit switch 165 is shown in the actuated position assumed when its actuating arm is in force-exerting contact with one of the bearing arms 152 of the bowling pins charging mechanism in its rearmost position.

It will be obvious, from an examination of the wiring diagram shown in the Fig. 54, that when the switches 300, 301, and 302, are closed, and the single pole double throw switches, 345 and 346, are positioned as is shown therein, the application of 110 volt alternating current to the bowling alley lighting circuit activates the bowling pin setting machine by energizing the operating coils of the main contactor 306 and of the ball elevating mechanism motor contactor 307. Under these conditions, if the bowling pins magazine latch-in relay 333 is in the detatched position, as is shown in the wiring diagram, the pushing, and temporarily holding pushed, of the set cycle bowler's push button 344 will energize the operating coil of the bowling pin setting cycle latch-in relay 331 and the forward operating coil of the three-phase reversing gear motor reversing contactor 314, starting the movement of the forward-and-reverse chain drive 173, causing the hinged bowling alley surface plates 179 to become tilted and deactivating the electric limit switch 216, opening its formerly closed contacts and closing its formerly opened contacts, thus latching in operating position the bowling pin setting cycle latch-in relay 331, which remains latched in until the reactivating of the electric limit switch 216 at the conclusion of the setting cycle.

It will also be obvious, from an examination of the wiring diagram shown in the Fig. 54, that while the bowling pin setting cycle latch-in relay 331 is in operating position, the reversing of the three-phase reversing gear motor 240 is controlled by the electric limit switch 197, the energization of the bowling pin traction magnets 193 are controlled by the electric limit switches 197, 198, 199, 75

and 200, and the energization of the solenoid-operated pusher member 164 is impossible.

Further examination of the wiring diagram shown in the Fig. 54 will disclose the fact that when the bowling pin setting machine is activated in the manner previously described, but is not engaged in the bowling pin setting cycle, the pushing, and temporarily holding pushed, of the "deadwood clearing" cycle bowler's push button 334 will energize the operating coil of the bowling pin "deadwood clearing" cycle latch-in relay 330 and the forward operating coil of the three-phase reversing gear motor reversing contactor 314, starting the movement of the forward-and-reverse chain drive 173, causing the hinged bowling alley surface plates 179 to become tilted and deactivating the electric limit switch 216, opening its formerly closed contacts and closing its formerly opened contacts, thus latching in operating position the bowling pin "deadwood clearing" cycle latch-in relay 330, which remains latched in until the reactivating of the electric limit switch 216 at the conclusion of the "deadwood clearing" cycle.

It will also be seen that, while the bowling pin "deadwood clearing" cycle latch-in relay 330 is in operating position, the reversing of the three-phase reversing gear motor 240 is controlled by the electric limit switch 218 and the energizations of the bowling pin traction magnets 193 are controlled by the bowling pins slave relay 324, all of whose contacts become closed upon the closing of the normally opened contacts of the bowling pin "deadwood clearing" cycle latch-in relay 330.

It will also be seen that energization of the solenoids 220 and deenergization of both of the hold-down magnets 223 and 224 is effected while the bowling pin "deadwood clearing" cycle latch-in relay 330 is in operating position, while deenergization of the hold-down magnet 223, without deenergization of the hold-down magnet 224, is effected while the bowling pin setting cycle latch-in relay 330 is in operating position, and that the simultaneous effectuation of the bowling pin "deadwood clearing" cycle and the bowling pin setting cycle cannot be accomplished.

It will further be noted that the consummation of a bowling pin charging cycle cannot occur until after the bowling pins magazine mechanism has been filled with bowling pins properly positioned therein and until after the bowling pins carrying and sweeping structure 170, once charged with bowling pins, has travelled to the bowling alley pit end of its travel in the bowling pins sweeping and setting cycle and has activated the electric limit switch 197 and has returned to the bowling pins carrying and sweeping structure receiving chamber 174 and until after the hinged bowling alley surface plates 179 have become detilted.

Operation of the present invention

Inasmuch as the descriptions of the various bowling pins and bowling balls handling mechanisms have been accompanied by descriptions of the modes of their operations, a description of the operations of the present invention, as a whole, from a selected starting point, can be described quite briefly.

At the start, it will be assumed: that the electric switches 300, 301, 302, are closed and the bowling alley lights are on, the hinged bowling pins spots plates 177 and the hinged bowling alley surface plates 179 are in their horizontal positions, wholly detilted; that a first set of ten bowling pins is set for play upon the hinged bowling pins spots plates 177, a second set of ten bowling pins is held within the bowling pins carrying and sweeping structure 170, and a third set of ten bowling pins is held upon the bowling pins magazine conveyor pans 122 of the bowling pins magazine mechanism. Under these conditions, the bowling pins and bowling balls handling mechanisms that are in operation are: the bowling alley gutter vibratory conveyors; the bowling alley pit vibratory conveyor; the first, second, and third endless chain lug conveyors, 79,

85, and 90, respectively, and the bowling pin injector mechanism, all driven directly or indirectly by the uni-directional gear motor 250: these four mechanisms are continuously in operation during utilization of the present invention.

"Deadwood clearing" cycle

A bowler bowls a ball and knocks down a number of bowling pins, some of which may be thus propelled into the bowling alley pit, or may be propelled onto the bowling alley gutter vibratory conveyors, and, by the bowling alley gutter vibratory conveyors, to be discharged into the bowling alley pit; and other of which (and occasionally bowling balls) may remain lying upon the hinged bowling alley surface plates 179 and upon the hinged bowling pins spots plates 177, amid such bowling pins as remain standing in playing positions upon the hinged bowling pins spots plates 177. These latter fallen pins are known as "deadwood"; and, to effect the clearance of the "deadwood," without disturbing the bowling pins standing in playing positions upon the bowling pins spots plates 177, the bowler pushes the "deadwood clearing" cycle bowler's push button 344, thus effectuating: the latching together of the pairs of hinged bowling alley surface plate 179 and bowling pins spots plate 177; the deenergizing of both of the hold-down magnets, 223 and 224, the energizing of the ten bowling pin traction magnets 193, and the initiating of the forward operation of the forward-and-reverse chain drive 173, which causes the latched-together pairs of hinged bowling alley surface plate 179 and hinged bowling pins spots plate 177 to become tilted, eventually to extents of 45 degrees, during which operation, the bowling pins that remained in playing positions after the bowling ball was bowled are held in their playing positions by the cooperating actions of the bowling pin traction magnets 193 and the armatures 194 in the bases of the bowling pins standing in playing positions, while the "deadwood" is discharged, by gravity, slidingly, from both pairs of latched-together hinged bowling alley surface plate 179 and hinged bowling pins spots plate 177 onto the bowling alley gutter vibratory conveyors, and, by the bowling alley gutter vibratory conveyors, discharged into the bowling alley pit. When the latched-together pairs of hinged bowling alley surface plate 179 and hinged bowling pin spot plate 177 have become tilted to extents of 45 degrees, the electric limit switch 218, becoming actuated by the lug 217 on the left forked crank arm 208, brings to a halt the forward operation, and starts the reverse operation, of the forward-and-reverse chain drive 173, which causes the pairs of latched-together hinged bowling alley surface plate 179 and hinged bowling pins spots plate 177 to become wholly detilted and horizontal, whereupon the electric limit switch 216, becoming actuated by the lug 215 on the right forked crank arm 208, effectuates the energizing of both of the hold down magnets, 223 and 224, the delatching of the pairs of hinged bowling alley surface plate 179 and hinged bowling pins spots plate 177, and the deenergizing of the ten bowling pin traction magnets 193, thus terminating the "deadwood clearing" cycle. The "deadwood clearing" cycle may, of course, be utilized when and as often as, desired.

Bowling pins setting cycle

Upon the completion of a frame or box of play, the bowler pushes the set cycle bowler's push button 343, thus effectuating: the deenergization of the single hold down magnet 223; the initiating of the forward operation of the forward-and-reverse chain drive 173, which causes the pair of hinged bowling alley surface plates 179 to become wholly tilted, and thereafter the bowling pins carrying and sweeping structure 170 to become elevated out of the bowling pins carrying and sweeping structure receiving chamber 174 and to become erected and to become carried rearwardly over the hinged bowling pins spots plates 177, sweeping before it, and into the bowling alley pit, bowling

pins and bowling balls that may be resting upon the hinged bowling pins spots plates 177, until the bowling pins carrying and sweeping structure 170 nears the edge of the bowling alley pit, actuating, by means of the right-hand double forked dog 171 thereon, the electric limit switch 197, thus effectuating: the setting of a part of the electrical circuit of the solenoid of the pusher member 164 of the bowling pins charging mechanism; the halting of the rear-ward movement, and the initiating of the front-ward movement, of the bowling pins carrying and sweeping structure 170 over the bowling pins spots plates 177, whereupon the electric limit switch 197, in its deactuating, effectuates the energizing of the four rearmost bowling pin traction magnets 193 in the hinged bowling pins spots plates 177, which cause the bowling pins 7, 8, 9, 10, in the bowling pins carrying and sweeping structure 170 to become immobilized in their playing positions upon the energized bowling pin traction magnets 193 in the hinged bowling pins spots plates 177, and to escape from the bowling pins carrying and sweeping structure 170, by, and in, its lateral displacement from the immobilized bowling pins, 7, 8, 9, 10. Upon further travel frontwardly, the bowling pins carrying and sweeping structure 170 similarly, and successively, actuates, by means of the right-hand doubly forked dog 171 thereon, the electric limit switches 198, 199, and 200, effectuating the energizing of the bowling pin traction magnets 193 for the bowling pins 4, 5, 6, 2, 3, and 1, respectively; and, thereafter, the bowling pins carrying and sweeping structure 170 is de-erected and lowered into the bowling pins carrying and sweeping structure receiving chamber 174, the wholly tilted hinged bowling alley surface plates 179 are detilted and become horizontal, and, through the actuation of the electric limit switch 216, the hold down magnet 223 becomes energized, thus terminating the bowling pins setting cycle. Ancillary to the concluding phases of the bowling pins setting cycle are the actuating of the pusher member 164 and the consequent operation of the bowling pins charging mechanism and the re-charging of the bowling pins carrying and sweeping structure 170, also effectuated by the actuating of the electric limit switch 216.

During all of these operations, the bowling alley pit vibratory conveyor has been transmitting, individually and unforcefully, bowling balls and bowling pins, indiscriminately base foremost and head foremost, through the ingress 49 into the pocket-like structure, wherein each bowling ball and each bowling pin, indiscriminately base foremost and head foremost, received therein, blocks the entry of another bowling ball or bowling pin thereinto, until it is removed therefrom by a lug 78 of the first (rear) endless chain lug conveyor 79 which impels it, upwardly, to the locus of the separating mechanism, where the bowling balls and bowling pins, indiscriminately base foremost and head foremost, are separated, each bowling ball rolling to the ball track 83 and each bowling pin becoming orientated and delivered onto the third (storage) endless chain lug conveyor, orientated head foremost in the direction of its possible travel, where it may be held under conditions of demand imposed by cooperating mechanisms, or it may be delivered through the bowling pin chute 92, the bowling pin chute receiving chamber 93, and the bowling pin injector mechanism, into the bowling pins magazine mechanism, which, in the completion of its filling or loading with bowling pins injected thereinto by the bowling pin injector mechanism, breaks the electrical circuit of the solenoid 253 of the one-revolution clutch, and thus the initial conditions, wherewith the exposition of the operation of the present invention began, are restored, save for the facts that the ten bowling pins now standing upon the hinged bowling pins spots plates 177 are the second set of ten bowling pins, the ten bowling pins in the bowling pins sweeping and carrying structure 170 are the third set of ten bowling pins, and the ten bowling pins in the bowling pins magazine mechanism

are the first set of ten bowling pins. When the balls delivered onto the ball track 83 have been returned to the bowler by way of the ball return 17 and the bowling ball elevating mechanism, which has been running continuously, all of the initial conditions are restored.

While preferred, and alternative, forms and arrangements of the mechanisms and elements of the present invention have been illustrated and described heretofore, it will be evident that numerous changes and modifications may be made in the forms, constructions, and arrangements of the parts of the present invention without departing from the spirit thereof. For example, the upper surfaces of the hinged bowling alley surface plates and of the hinged bowling pins spots plates may be veneered with wood, in order to simulate more closely the usual playing surfaces of bowling alleys; and the upper surfaces of the longitudinal members of the bowling alley gutter vibratory conveyors may be veneered with wood and/or contoured, in order to more closely simulate the usual upper surfaces of bowling alley gutters. It should, therefore, be understood that the embodiments of the present invention, and of portions thereof, herein described and shown in the drawings, are intended to be illustrative of the invention, and are not intended to limit the scope thereof.

Having thus described our invention, we claim:

1. In a bowling pin setting machine, a bowling pins carrying and sweeping mechanism comprising, in combination: a bowling pins carrying and sweeping structure, adapted to hold releasably, in horizontal travel over the bowling pins spots positions of the playing surface of a bowling alley, bowling pins maintained uprightly therein; means for supporting and carrying over the bowling pins spots positions of the playing surface of the bowling alley the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions; and control means for activating the bowling pin arresting devices, distributed between the bowling alley and the bowling pins carrying and sweeping structure and actuatable by the bowling pins carrying and sweeping structure in its horizontal travel over the bowling pins spots positions of the playing surface of the bowling alley.

2. In a bowling pin setting machine, a bowling pins carrying and sweeping mechanism comprising, in combination: a bowling pins carrying and sweeping structure, adapted to sweep bowling pins and bowling balls off of the playing surface comprising the bowling pins spots positions of a bowling alley, and adapted to hold releasably, in horizontal travel over the bowling pins spots positions of the playing surface of the bowling alley, bowling pins maintained uprightly therein; means for supporting and carrying over the bowling pins spots positions of the playing surface of the bowling alley the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions; and control means for activating the bowling pin arresting devices, distributed between the bowling alley and the bowling pins carrying and sweeping structure in its horizontal travel over the bowling pins spots positions of the playing surface of the bowling alley.

3. In a bowling pin setting machine, a bowling pins carrying and sweeping mechanism comprising, in combination: a bowling pins carrying and sweeping structure, adapted, in horizontal travel rearwardly over the playing surface comprising the bowling pins spots positions of a bowling alley to sweep bowling pins and bowling

balls therefrom, and adapted to hold releasably, in horizontal travel forwardly over the bowling pins spots positions of the playing surface of the bowling alley, bowling pins maintained uprightly therein; means for supporting and carrying, in horizontal travel rearwardly and in horizontal travel forwardly over the playing surface comprising the bowling pins spots positions of the bowling alley, the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions; and control means for activating the bowling pin arresting devices, distributed between the bowling alley and the bowling pins carrying and sweeping structure and actuatable by the bowling pins carrying and sweeping structure in its horizontal travel forwardly over the bowling pins spots positions of the playing surface of the bowling alley.

4. In a bowling pin setting machine, a bowling pins carrying and sweeping mechanism comprising, in combination: a bowling pins carrying and sweeping structure, adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the bowling pins spots positions of the playing surface of the bowling alley, the bowling pins carrying and sweeping structure; bowling pin arresting devices, embedded in the playing surface of the bowling alley at the bowling pins spots positions, each bowling pin arresting device being adapted, when activated, to immobilize against translation thereover, a bowling pin provided with construction capable of cooperating with, when positioned over, the bowling pin arresting device; and control means for activating the bowling pin arresting devices, distributed between the bowling alley and the bowling pins carrying and sweeping structure and actuatable by the bowling pins carrying and sweeping structure in its translation in forwardly directed motion over the bowling pins spots positions of the playing surface of the bowling alley.

5. In a bowling pin setting machine, a bowling pins carrying and sweeping mechanism comprising, in combination: a bowling pins carrying and sweeping structure, adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the bowling pins spots positions of the playing surface of the bowling alley, the bowling pins carrying and sweeping structure; bowling pin traction magnets, embedded in the playing surface of the bowling alley at the bowling pins spots positions, each adapted, when energized, to immobilize against translation thereover, a bowling pin provided with an armature element, when positioned upon the bowling pin traction magnet; and switch means for activating the bowling pin traction magnets, positioned upon the bowling alley and adapted to be actuated by the bowling pins carrying and sweeping structure in its translation in forwardly directed motion over the bowling pins spots positions of the playing surface of the bowling alley.

6. In a bowling pin setting machine, a bowling pins carrying and sweeping mechanism comprising, in combination: a bowling pins carrying and sweeping structure, adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the

bowling pins spots positions of the playing surface of the bowling alley, the bowling pins carrying and sweeping structure; solenoid-actuated bowling pin spotter pegs, embedded in the playing surface of the bowling alley at the bowling pins spots positions, each adapted, when activated, to immobilize against translation thereover, a bowling pin provided with a cavity venting through its bottom surface wherein to receive the bowling pin spotter peg when the bowling pin is positioned upon the solenoid-actuated bowling pin spotter peg; and switch means for activating the solenoid-actuated bowling pin spotter pegs, positioned upon the bowling alley and adapted to be actuated by the bowling pins carrying and sweeping structure in its translation in forwardly directed motion over the bowling pins spots positions of the playing surface of the bowling alley.

7. In a bowling pin setting machine, a bowling pins carrying and sweeping mechanism comprising, in combination: a bowling pins carrying and sweeping structure, adapted to be received into a chamber located below the playing surface of a bowling alley and there to receive bowling pins thereinto; and adapted to hold releasably, in translation in forwardly directed motion over the bowling pins spots positions of the playing surface of the bowling alley, bowling pins maintained uprightly therein; means for venting the playing surface of the bowling alley above the chamber located below the playing surface of the bowling alley to provide an entrance and exit for the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions; means for elevating and erecting the bowling pins carrying and sweeping structure out of the chamber located below the playing surface of the bowling alley and for supporting and carrying the bowling pins carrying and sweeping structure, in translation in rearwardly directed motion over the playing surface comprising the bowling pins spots positions of the bowling alley, sweeping bowling pins and bowling balls therefrom, and for supporting and carrying, in translation in forwardly directed motion over the bowling pins spots positions of the playing surface of the bowling alley, the bowling pins carrying and sweeping structure, releasing bowling pins upon bowling pins spots positions; control means for activating the bowling pin arresting devices, distributed between the bowling alley and the bowling pins carrying and sweeping structure and actuatable by the bowling pins carrying and sweeping structure in its translation in forwardly directed motion over the bowling pins spots positions of the playing surface of the bowling alley; means for deerecting and lowering the bowling pins carrying and sweeping structure into the chamber located below the playing surface of the bowling alley; and means for restoring the playing surface of the bowling alley above the chamber located below the playing surface of the bowling alley.

8. In a bowling pin setting machine, a bowling pins carrying and sweeping mechanism comprising, in combination: a bowling pins carrying and sweeping structure, provided with a chamber, bottomless and venting through a lateral aperture in the bowling pins carrying and sweeping structure, and adapted to receive into the chamber, tandemwise, and to hold releasably therein, in horizontal travel over the bowling pins spots positions of the playing surface of a bowling alley, a pair of bowling pins, maintained uprightly therein; means for supporting and carrying over the bowling pins spots positions of the playing surface of the bowling alley the bowling pins carrying and sweeping structure; bowling pin arresting devices, embedded in the playing surface of the bowling alley at bowling pins spots positions and capable of cooperating with bowling pins to effect arrests of bowling pins upon bowling pins spots positions; and control means for

activating the bowling pin arresting devices, distributed between the bowling alley and the bowling pins carrying and sweeping structure and actuatable by the bowling pins carrying and sweeping structure in its horizontal travel over the bowling pins spots positions of the playing surface of the bowling alley.

9. In a bowling pin setting machine, a movable bowling pins carrying structure adapted to receive and to releasably hold a full set of bowling pins, with the full set of bowling pins disposed in a non-triangular relation, so that by a predetermined movement of the thus loaded bowling pins carrying structure over a portion of the bowling alley playing surface that is provided with a triangular arrangement of bowling pins spots positions individual bowling pins will be positioned uprightly upon the respective bowling pins spots positions, means to effect such predetermined movement of the thus loaded bowling pins carrying structure, and means to effect releases of the bowling pins so as to leave the bowling pins standing upon the said bowling pins spots positions when the bowling pins carrying structure is moved away from the said bowling pins spots positions.

10. In a machine for setting bowling pins upon the bowling pins spots positions of a portion of the playing surface of a bowling alley, a bowling pins carrying and setting structure movable horizontally over the said portion of the bowling alley playing surface which is provided with bowling pins spots positions, the said bowling pins carrying and setting structure having chambers corresponding in number with the bowling pins spots positions and each adapted to hold releasably therein an upright bowling pin with the bottom surface of the bowling pin close to the bowling alley playing surface, the said chambers being arranged in relation to one another and to the positions of the individual bowling pins spots positions of the said portion of the bowling alley playing surface which is provided with bowling pins spots positions so that a given horizontal movement of the bowling pins carrying and setting structure over the said portion of the bowling alley playing surface which is provided with bowling pins spots positions will bring and individual bowling pins in the chambers to positions directly over and in register with the respective bowling pins spots positions, means to arrest further horizontal movement of any of the said bowling pins by the bowling pins carrying and setting structure when any such bowling pin has been thus positioned with respect to one of the bowling pins spots positions, and means to effect the release of each thus arrested bowling pin from its chamber so as to leave the said bowling pin standing upon the said bowling pins spots position as the horizontal movement of the bowling pins carrying and sweeping structure is continued.

11. In a machine for setting bowling pins upon the conventionally located ten bowling pins spots positions on a portion of the playing surface of a bowling alley, a bowling pins carrier member comprising an elongate horizontal structure adapted to be disposed transversely of the bowling alley playing surface and to be moved therealong over the said portion of the bowling alley playing surface, the said elongate horizontal structure being so formed as to provide therein a first row of seven bowling pin-accommodating chambers spaced along the elongate horizontal structure and a second row of three bowling pin-accommodating chambers parallel with and forwardly of the middle three chambers of the first row of seven bowling pin accommodating chambers, the axes of the said chambers being vertical when the elongate horizontal structure is disposed transversely of the bowling alley playing surface, and each of the said chambers being open at its bottom to permit the descent therein of a bowling pin until the bottom surface of such bowling pin rests upon the bowling alley playing surface and each of the said chambers being so formed as to provide an opening through which, when unobstructed, an upright

bowling pin resting upon the bowling alley playing surface may pass horizontally out of the said chamber, a yieldable bowling pin engaging element being provided in association with the said chamber to prevent such outward passage until actuated by an overpowering force, means to move the elongate horizontal structure with upright bowling pins disposed in the chambers thereof over the said portion of the bowling alley playing surface so as to bring the bowling pins in the said chambers to positions to rest upon the individual bowling pins spots positions, and means effective upon such positioning of the bowling pins to exert through the bowling pins an overpowering force upon the yieldable bowling pin engaging elements of the chambers to cause such yieldable bowling pin engaging elements to yield so as to leave the bowling pins standing upon the bowling pins spots positions as the elongated horizontal structure is moved away from such bowling pins spots positions.

12. The combination specified by claim 11 wherein the means for exerting upon the bowling pins an overpowering force on the yieldable bowling pin engaging elements comprises magnetizable inserts in the bottom portions of the bowling pins and selectively controlled electromagnets operatively associated with the bowling pins spots positions of the the bowling alley playing surface.

13. The combination specified by claim 11 wherein an elongate horizontal structure-accommodating chamber is provided below the level of the bowling alley playing surface and the means for moving the elongate horizontal structure over the bowling alley playing surface is operable to move the elongate horizontal structure into such elongate horizontal structure-accommodating chamber after each bowling pins setting operations by the use of the elongate horizontal structure and to turn such elongate horizontal structure angularly about its longitudinal axis to dispose the chambers thereof in horizontal positions for loading with bowling pins when the elongated horizontal structure is in the elongated horizontal structure-accommodating chamber.

14. In a bowling pin setting machine, a bowling pins carrying member comprising an elongate structure adapted to receive and to releasably retain therein a set of bowling pins suitable for setting upon the bowling pins spots positions of a bowling alley playing surface, means to support said elongate structure disposed transversely of the said bowling alley playing surface so that the said elongate structure thus disposed transversely of the said bowling alley playing surface is movable in the directions thereof and close thereto, means for moving the said elongate structure rearwardly from a position in advance of the region of the bowling pins spots positions over the region of the bowling pins spots positions to a position adjacent to the rear end of the bowling alley playing surface and then forwardly from the position adjacent to the rear end of the bowling alley playing surface over the region of the bowling pins spots positions to the initially specified position, means to assure retention of the bowling pins in the elongate structure during the rearward movement thereof during which the elongate structure serves as a sweep to clear deadwood from the rearwardly and forwardly traversed portion of the bowling alley playing surface, and means controlling releases of the bowling pins from the elongate structure to effect such releases of the individual bowling pins onto bowling pins spots positions during the movement forwardly of the elongate structure.

15. In a bowling pin setting machine, a bowling pins carrying and sweeping mechanism comprising, in combination: a bowling pins carrying and sweeping structure having bowling pin holding chambers venting through lateral apertures provided with spring loaded doors and adapted to hold releasably, in horizontal travel over the bowling pins spots positions of the playing surface of a bowling alley, bowling pins maintained uprightly therein; means for supporting and carrying over the bowling pins

spots positions of the playing surface of the bowling alley the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions and releases of bowling pins from the bowling pins carrying and sweeping structure through the lateral apertures therein and the spring loaded doors thereof; and control means for activating the bowling pin arresting devices, distributed between the bowling alley and the bowling pins carrying and sweeping structure and actuatable by the bowling pins carrying and sweeping structure in its horizontal travel over the bowling pins spots positions of the playing surface of the bowling alley.

16. In a bowling pin setting machine, a bowling pins carrying and sweeping mechanism comprising, in combination, a bowling pins carrying and sweeping structure having bowling pin holding chambers venting through lateral apertures provided with spring loaded doors, adapted to sweep bowling pins and bowling balls off of the playing surface comprising the bowling pins spots positions of the playing surface of a bowling alley and adapted to hold releasably, in horizontal travel over the bowling pins spots positions of the playing surface of the bowling alley, bowling pins maintained uprightly therein; means for supporting and carrying over the bowling pins spots positions of the playing surface of the bowling alley the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions and releases of bowling pins from the bowling pins carrying and sweeping structure through the lateral apertures therein and the spring loaded doors thereof; and control means for activating the bowling pin arresting devices, distributed between the bowling alley and the bowling pins carrying and sweeping structure and actuatable by the bowling pins carrying and sweeping structure in its horizontal travel over the bowling pins spots positions of the playing surface of the bowling alley.

17. In a bowling pin setting machine, a bowling pins carrying and sweeping mechanism comprising, in combination: a bowling pins carrying and sweeping structure having bowling pin holding chambers venting through lateral apertures provided with spring loaded doors, adapted, in horizontal travel rearwardly over the playing surface comprising the bowling pins spots positions of a bowling alley to sweep bowling pins and bowling balls therefrom, and adapted to hold releasably, in horizontal travel forwardly over the bowling pins spots positions of the playing surface of the bowling alley, bowling pins maintained uprightly therein; means for supporting and carrying, in horizontal travel rearwardly and in horizontal travel forwardly over the playing surface comprising the bowling pins spots positions of the bowling alley, the bowling pins carrying and sweeping structure; bowling pin arresting devices, embedded in the playing surface of the bowling alley at the bowling pins spots positions and capable of cooperating with bowling pins to effect arrests of bowling pins upon bowling pins spots positions and releases of bowling pins from the bowling pins carrying and sweeping structure through the lateral apertures therein and the spring loaded doors thereof; and control means for activating the bowling pin arresting devices, distributed between the bowling alley and the bowling pins carrying and sweeping structure and actuatable by the bowling pins carrying and sweeping structure in its horizontal travel forwardly over the bowling pins spots positions of the playing surface of the bowling alley.

18. In a bowling pin setting machine, a bowling pins carrying and sweeping mechanism comprising, in combination: a bowling pins carrying and sweeping structure having bowling pin holding chambers venting through lateral apertures provided with spring loaded doors,

adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the bowling pins spots positions of the playing surface of the bowling alley, the bowling pins carrying and sweeping structure; bowling pin arresting devices, embedded in the playing surface of the bowling alley at the bowling pins spots positions, each bowling pin arresting device being adapted, when activated, to immobilize against translation thereover, a bowling pin provided with construction capable of cooperating with, when positioned over, the bowling pin arresting device, and thus to effect the release, from the bowling pins carrying and sweeping structure through a lateral aperture therein and its spring loaded doors, of such bowling pin within a bowling pin holding chamber thereof, when in translation in forwardly directed motion of the bowling pins carrying and sweeping structure over the bowling pins spots positions, such bowling pin becomes positioned over the bowling pin arresting device; and control means for activating the bowling pin arresting devices, distributed between the bowling alley and the bowling pins carrying and sweeping structure and actuatable by the bowling pins carrying and sweeping structure in its translation in forwardly directed motion over the bowling pins spots positions of the playing surface of the bowling alley.

19. In a bowling pin setting machine, a bowling pins carrying and sweeping mechanism comprising, in combination: a bowling pins carrying and sweeping structure having bowling pin holding chambers venting through lateral apertures provided with spring loaded doors, adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the bowling pins spots positions of the playing surface of the bowling alley the bowling pins carrying and sweeping structure; bowling pin traction magnets, embedded in the playing surface of the bowling alley at the bowling pins spots positions, each bowling pin traction magnet being adapted, when energized, to immobilize against translation thereover, a bowling pin provided with an armature element, when such bowling pin is positioned upon the bowling pin traction magnet, and thus to effect the release, from the bowling pins carrying and sweeping structure through a lateral aperture therein and its spring loaded doors, of such bowling pin within a bowling pin holding chamber thereof, when in translation in forwardly directed motion of the bowling pins carrying and sweeping structure over the bowling pin spots position, such bowling pin becomes positioned upon the bowling pin traction magnet; and switch means for activating the bowling pin traction magnets, positioned upon the bowling alley and adapted to be actuated by the bowling pins carrying and sweeping structure in its translation in forwardly directed motion over the bowling pins spots positions of the playing surface of the bowling alley.

20. In a bowling pin setting machine, a bowling pins carrying and sweeping mechanism comprising, in combination: a bowling pins carrying and sweeping structure having bowling pin holding chambers venting through lateral apertures provided with spring loaded doors, adapted to hold releasably, in translation in forwardly directed motion over the bowling pins spots positions of the playing surface of a bowling alley, bowling pins maintained uprightly therein; means for supporting and carrying, in translation in rearwardly directed motion and in translation in forwardly directed motion over the bowling pins spots positions of the playing surface of the bowling alley the bowling pins carrying and sweeping structure; solenoid-actuated bowling pin spotter pegs, em-

bedded in the playing surface of the bowling alley at the bowling pins spots positions, each solenoid-actuated bowling pin spotter peg being adapted, when activated, to immobilize against translation thereover, a bowling pin provided with a cavity venting through its bottom surface wherein to receive the bowling pin spotter peg when such bowling pin is positioned upon the solenoid-actuated bowling pin spotter peg, and thus to effect the release, from the bowling pins carrying and sweeping structure through a lateral aperture therein and its spring loaded doors, of such bowling pin within a bowling pin holding chamber thereof, when in translation in forwardly directed motion of the bowling pins carrying and sweeping structure over the bowling pins spots positions, such bowling pin becomes positioned upon the solenoid-actuated bowling pin spotter peg; and switch means for activating the solenoid-actuated bowling pin spotter pegs, positioned upon the bowling alley and adapted to be actuated by the bowling pins carrying and sweeping structure in its translation in forwardly directed motion over the bowling pins spots positions of the playing surface of the bowling alley.

21. In a bowling pin setting machine, a bowling pins carrying and sweeping mechanism comprising, in combination: a bowling pins carrying and sweeping structure having a bowling pins holding chamber venting through a lateral aperture provided with spring loaded doors and adapted to receive into the bowling pins holding chamber, tandemwise, and to hold releasably therein, in horizontal travel over the bowling pins spots positions of the playing surface of a bowling alley, a pair of bowling pins, maintained uprightly therein; means for supporting and carrying over the bowling pins spots positions of the playing surface of the bowling alley the bowling pins carrying and sweeping structure; bowling pin arresting devices, embedded in the playing surface of the bowling alley at the bowling pins spots positions, each bowling pin arresting device being adapted, when activated, to immobilize against translation thereover, a bowling pin provided with construction capable of cooperating with, when positioned over, the bowling pin arresting device, and thus to effect the release, from the bowling pins carrying and sweeping structure through the lateral aperture therein and the spring loaded doors thereof, of such bowling pin within the bowling pins holding chamber thereof, when in translation in forwardly directed motion of the bowling pins carrying and sweeping structure over the bowling pins spots positions of the playing surface of the bowling alley, such bowling pin becomes positioned over the bowling pin arresting device; and control means for activating the bowling pin arresting devices, distributed between the bowling alley and the bowling pins carrying and sweeping structure and actuatable by the bowling pins carrying and sweeping structure in its translation in forwardly directed motion over the bowling pins spots positions of the playing surface of the bowling alley to effect the immobilization of each bowling pin upon a bowling pins spots position and the successive releases of the bowling pins from the bowling pins carrying and sweeping structure through the lateral aperture therein and the spring loaded doors thereof.

22. In a bowling pin setting machine, a bowling pins carrying mechanism comprising, in combination: a bowling pins carrying structure adapted to be received into a chamber located wholly within the bowling alley bed construction forwardly of the bowling pins spots positions of the playing surface of a bowling alley and there to receive bowling pins thereinto; doors, constituting the portion of the playing surface of the bowling alley above the chamber located wholly within the bowling alley bed construction forwardly of the bowling pins spots positions of the playing surface of the bowling alley, adapted to provide an egress and an ingress for the bowling pins carrying structure; means for elevating and erecting the bowling pins carrying structure out of, and for deerecting

and lowering the bowling pins carrying structure into, the chamber located wholly within the bowling alley bed construction forwardly of the bowling pins spots positions of the playing surface of the bowling alley; and means for opening and for closing the doors, constituting the portion of the playing surface of the bowling alley above the chamber located wholly within the bowling alley bed construction forwardly of the bowling pins spots positions of the playing surface of the bowling alley.

23. In a bowling pins carrying mechanism of a bowling pin setting machine, means for housing a bowling pins carrying structure comprising, in combination: a chamber located wholly within the bowling alley bed construction forwardly of the bowling pins spots positions of the playing surface of a bowling alley and adapted to receive 15 thereinto a bowling pins carrying structure; doors, constituting the portion of the playing surface of the bowling alley above the chamber located wholly within the bowling alley bed construction forwardly of the bowling pins spots positions of the playing surface of the bowling alley,

10 15 20

adapted to provide an egress and an ingress for the bowling pins carrying structure; means for elevating a bowling pins carrying structure out of, and for lowering a bowling pins carrying structure into, the chamber located wholly within the bowling alley bed construction forwardly of the bowling pins spots positions of the playing surface of the bowling alley; and means for opening and for closing the doors constituting the portion of the playing surface of the bowling alley above the chamber located wholly within the bowling alley bed construction forwardly of the bowling pins spots positions of the playing surface of the bowling alley.
